UNITED STATES PATENT OFFICE

HERBERT M. FRIENDLY, OF CHICAGO, ILLINOIS; MILTON S. FRIENDLY AND CENTRAL TRUST COMPANY OF ILLINOIS EXECUTORS OF SAID HERBERT M. FRIENDLY, DECEASED

AUTOMATIC TELEPHONE SYSTEM

Application filed February 27, 1928. Serial No. 257,480.

The present invention relates to telephone systems; more particularly so-called automatic or machine switching telephone systems.

General objects

The general objects of the present invention are to enable a subscriber of the automatic telephone system, who contemplates temporarily leaving the location of his telephone, to directively set central office apparatus or call-forwarding equipment associated with his line through the agency of his automatic calling device dial on his telephone so that in case any calls are thereafter directed to his line, the latter said calls will be further extended or forwarded to a predetermined random subscriber's line or other line of the system. The latter said line may terminate at the switchboard of an attendant operator who is charged with responding to such calls and imparting such information to the party calling as instructed by the absent subscriber primarily called. That is, for example, a physician before leaving his office may remove the receiver of his telephone as if to initiate a call, and then operate his calling device dial by placing his forefinger in a specific depression finger-hold of the dial and then draw the dial until his finger encounters the finger-stop, so that when the dial is released it will send a series of eleven open impulses. After the dial has returned, he will restore the receiver, leaving his central office call-forwarding equipment in the set condition. The same kind of manual operation will un-set the said set condition.

General operation

Reference is made to my Patent No. 1,772,713, granted Aug. 12, 1930. Also, to my Patent No. 1,800,788 granted April 14, 1931. These pending applications are directed to a telephone system and apparatus having objects generally as set forth in the foregoing statements. However, the present invention is directed to a telephone system having features and objects not present in the disclosures in the foregoing references, while at the same time the

said reference applications incorporate features looking to objects not disclosed in the present application. These latter features may be incorporated in the present disclosure. In general, it may be stated that the present invention, as compared to the disclosures in said applications made of reference, looks to reducing the amount of equipment through employing certain elements in common with a plurality of lines arranged for forwarding calls in place of employing equipment used solely for an individual line. There are a number of other features of the present invention not present in the applications made of reference in the fore-going. Among the said other features are:

a. An impulse sending mechanism for directing the forwarding of calls which mechanism is common to a plurality of lines arranged so that calls made to a random one of said lines may be forwarded to a predetermined line or lines of the system, directed by the common impulse sending mechanism.

When a call is made to a line set for forwarding the call, a relay specific to said line is operated, to in turn cause a finder switch to initiate its operation and select and seize the line called and thereby extend the line called to a first selector, or selector of the lowest rank in the system. Incidental to selecting and seizing the called line, apparatus is prepared for sending a train of impulse series which is predetermined in accordance with the line to which such calls are to be sent by pre-arrangement. The present disclosure shows two methods of accomplishing the sending of the proper train of series corresponding to the line called primarily by the calling party.

The first method which will be described contemplates an impulse sending mechanism individual to a finder switch. The finder switch will hunt for and seize the called line set for forwarding responsive to said set called line being seized by the connector directed by the calling party. Each said impulse sending mechanism contains as many relays as there are called lines to be served or embraced by the finder switch. When the finder switch sweeps bank terminals by its

wipers and finds the set line under call, one of the said wipers is then resting upon a bank terminal which corresponds to the winding of a relay specific to the line under call. 5 Under the seized condition of the finder switch this relay will be operatively energized so that its contacts will close circuit paths for setting up a stored condition in the impulse sending mechanism for sending 10 a train of series which will operate the first selector and successive switches to forward the call from the line primarily called to the line which is to finally receive the call because of the set condition of the line primarily called. 15

The said first method, because of having an impulse sending mechanism individual to the finder switch, thus disables the impulse sending mechanism from further use until the 20 finder switch becomes idle due to the termination of the call last forwarded.

The second, or preferred method, which will be described later on, contemplates a 25 finder switch generally like the finder switch used in the said first method, but in place of having an impulse sending mechanism individual to the finder switch, has a group of three impulse sending mechanisms (in the exemplary embodiment disclosed herein) 30 common to a larger plurality of said finder switches. The latter said plurality may be fifty or more, depending upon the traffic to be handled.

Under the said preferred method, when the 35 call is progressed to a set called line, one of the finder switches will hunt for and seize the said set called line. Responsive to the latter said seizure of the set called line a second finder switch individual to one of the said 40 three impulse sending mechanisms will start its hunting operation to find and seize the finder switch which last operated to seize the set line called. When this finder switch, or any other finder switch not yet co-operated 45 with an impulse sending mechanism, is found and seized by the said second finder switch, a relay individual to the set line called and corresponding to the relay used in the said first method, is operatively energized to set 50 the impulse sending mechanism individual to the said second finder switch so that a train of impulse series is thereupon sent to forward the call to the predetermined line of the system which is to finally receive the call. The 55 preferred method is essentially like the said first method, in so far as the impulse sending mechanism is concerned, since each said mechanism contains a relay specific to each line which may be primarily called by a calling party which also may be set for forwarding calls. However, a second finder switch is interposed for co-operating a common said 60 mechanism with a random one of a plurality of first finder switches arranged for co-operating with a set line called.

b. A connector J is shown having access to operator answering jacks. These jacks are on an attendant operator's switchboard. The operator will perceive calls to the respective jacks by the glowing of a companion lamp when a call is forwarded from a line primarily called which said line has been set so that the call will be forwarded to the jack on the attendant's switchboard specific to it. That is to say, the connector J is reached by the impulse sending mechanism sending an impulse train constituting three digits "111". These three digits will be followed by a series constituting two more digits to operate the connector J to select the desired answering jack. The last two digit series thus identifies the line of a hundred-group which was primarily called by the calling party. The attendant will be able to respond with a full knowledge of the line which was primarily called. She may take any message for the wanted subscriber or give any instructed information. 70 75 80 85

c. A feature of the connector J, and those of its group not shown, is the provision for permitting successive connectors to select the same answering jack and apply a busy tone to the calling party while barring a talking connection with the jack if a talking connection already exists to the jack through some other connector. Under the condition of the calling party receiving the busy tone he may await his turn, as he will be able to gain talking connection with the jack only in the corresponding time order in which the jack was selected by a waiting connector. When the attendant withdraws the answering plug to terminate a conversation the jack will be seized from the next in order waiting connector. The said order of waiting is determined by the order of calling through the agency of order of access switches which constantly predetermine the order of access in accordance with the order of selecting the jack, automatically. The latter takes into account any calls which may be abandoned without upsetting the relative order of access. Under the arrangement a single jack is provided specific for each subscriber to the attendant's services regardless of the number of calls which may be held in abeyance each with its attained order of access, at the same time. 90 95 100 105 110 115

d. Means are provided for apprising the attendant while she is in communication with a calling party if there is any other party (or parties) awaiting his turn to be responded to by her, so that she may dispose of the party then in communication as soon as possible in view of the party or parties awaiting their turn for a response from her through the same jack as then in use. 120 125

There are a number of other features of the present invention believed to be novel, and which will be described in detail herein- 130

after, or will be apparent in view of the descriptions and accompanying drawings.

Drawings

With reference to the accompanying drawings:—

Fig. 1 shows a calling telephone A leading-in to a line switch B. It also shows the set relay C for changing the so-termed normal conductors from the line leading to the line switch B to the corresponding bank terminals accessible from line finder switch F in Fig. 3. The indicated connector D normally has access to the line leading to telephone A.

Fig. 2 shows a first selector E of a group accessible from the line switch B. It also indicates a calling telephone A² leading to a line switch L², the latter having access to first selector B², second selector C², third selector D², and connector D in Fig. 1, in sequence, to complete a call from the telephone A² in Fig. 2 to the telephone A in Fig. 1.

Fig. 3 shows a line finder switch F of the present invention involving auxiliary apparatus, the said line finder switch having access to terminals of a plurality of lines which may be called through connector D in Fig. 1, or random connectors in the exchange office containing connector D wherein contact springs of a set relay similar to C are interposed. Each said line accessible from line switch F has a line relay as shown on the left aligned with the switch relays.

Fig. 4 shows a first selector G companion to and individual to the line finder switch F in Fig. 3. The first selector F has access to other switches in common with first selector E in Fig. 2. The first level of selectors E and F have common access to the secondary line switch SL⁴. The second level of selectors E and F have common access to second selector B⁴, third selector C⁴ and connector D⁴ in sequence, the latter having access to the line leading to telephone A⁴. The third level of selectors E and F have common access to second selector B⁴, third selector F⁴ and connector G⁴ in sequence, the latter having access to the line leading to telephone A⁴.

Fig. 5 shows a second selector H reached through the secondary line switch SL⁴. It also shows a third selector I reached from the second selector H.

Fig. 6 shows a connector of the present invention J reached through the third selector I. The connector J has access to operators' answering jacks, two of which jacks are shown.

Fig. 6A shows an operator's answering plug and associated operator's telephone circuit. The said plug is co-operative with the answering jacks shown in Fig. 6.

Fig. 7 shows three order of access switches K, L, and M, of a group which switches are co-operative with the group or groups of connectors of which connector J is one.

Fig. 8 shows the impulse sending mechanism for directing the forwarding of calls.

Fig. 9 shows a preferred modification Q of the line finder switch F.

Fig. 10 shows the line finder switch R individual to the impulse sending mechanism shown in Fig. 8, when assembled in the preferred embodiment.

Fig. 11 shows the line finder switch S individual to one of the group of impulse sending mechanisms, only one of the latter (Fig. 8) being shown.

Fig. 12 shows the line finder switch T individual to one of the group of impulse sending mechanism, only one of the latter (Fig. 8) being shown.

Fig. 13 shows one of the wipers and co-operative bank terminals of the predetermined switch for governing the number of impulses in the train of impulse series sent.

Fig. 14 shows the circuit diagram employing the predetermined switch shown in Fig. 13 to obviate using jumpers in Fig. 8. This circuit concerns one of the set relays (802) in Fig. 8.

Fig. 15 shows a preferred modification of Figs. 1, 9, 10, 11, and 12, for applying an all-busy tone, and for other objects.

Fig. 16 shows a modification of the connection of the attendant's jack shown in Fig. 6, introduced where indicated by the section line a.

Fig. 17 shows a preferred modification of Fig. 6 for preventing more than one bar conductor from being unbarred at a time.

Fig. 18 shows the assembly of the figures to display the said first method of employing the present invention.

Fig. 19 shows the assembly of the figures to display the said preferred method of employing the present invention.

The various figures are assembled in accordance with the arrangements shown in Figs. 18 and 19, so that the lines extending towards the margins register.

Equipment

The telephone A in Fig. 1 is the well known common battery series type, but is equipped with an automatic calling device and dial as disclosed in my said Patent No. 1,772,713 and illustrated in Figs. 7 and 8 thereof. The dial enables a series of eleven open impulses to be sent responsive to operating and releasing a specific finger-hold depression Z positioned after the "0" digit finger-hold.

The line switch B in Fig. 1 is of the well known rotary class as described on page 53 of Hershey's Automatic Telephone Practice, third edition. However, the line switch B has an added upper wiper for objects of the present invention.

The connector D in Fig. 1 is of the well

known type as shown in Fig. 73 of the fourth edition of the said book.

The first selector E in Fig. 2 is of the well known type sometimes called a Powell selector, and described on pages 59 to 61 of the said third edition of Hershey's book. However, a set of eleventh vertical position off-normal springs and connected circuits belong to the present invention.

10 The first selector G in Fig. 4 is of the well known said Powell type.

The selectors B², C², and D² in Fig. 2; B⁴, C⁴, E⁴, F⁴ and G⁴ in Fig. 4, and H and I in Fig. 5, are like selector G in Fig. 4.

15 The line switch L² in Fig. 2 is like switch B in Fig. 1.

The connectors D⁴ and G⁴ in Fig. 4 are like connector D in Fig. 1.

20 The line finder switch F in Fig. 3 is of the class shown and described on pages 55 to 57 of the third edition of Hershey's book. However, modified in accordance with the present invention.

25 The connector J in Fig. 6 is of the class of connector D in Fig. 1. However, modified in accordance with the present invention. The operator's circuit shown in Fig. 6A is well known, or may be any suitable or other well known one.

30 The switch elements shown in Fig. 7 belong to the class of switch B in Fig. 1, modified in accordance with the present invention.

35 The switch elements N and O in Fig. 8 belong to the class of switch B in Fig. 1, modified in accordance with the present invention.

40 The finder switch Q in Fig. 9 is generally like switch F in Fig. 3, modified in accordance with the present invention.

Fig. 10 shows a finder switch R generally like the finder switch shown and described on pages 55 to 57 of the third edition of Hershey's book. However, modified in accordance with the present invention.

45 Fig. 11 shows a finder switch S, like R.

Fig. 12 shows a finder switch T, like R.

It will be understood that any other suitable switches may be substituted for the said well known switches mentioned, without departing from the spirit of the present invention. Also, that the switches specific to the present invention may be modified by those skilled in the art without departing from the spirit of the present invention, as defined by the subjoined claims.

It will, of course, be understood that in a commercial embodiment of the present invention a plurality of switches in a group 50 will be employed in place of the exemplary single switches used in disclosing the present invention, so that a plurality of calls may be co-existent, the switches in the groups having predetermined order of use with respect to 55 antecedent co-operative switches.

Detailed operation—Initiating a call from telephone A to telephone A'

Upon removing the receiver from the switch-hook of telephone A, the line switch B will operate in the well known manner to seize the first idle first selector E. The calling party will then operate his calling device in accordance with the five digits 34341 and thus correspondingly set the selectors E, E⁴ and F⁴ and connector G⁴. The connection may then be released in the well known manner, responsive to the calling party replacing his receiver on the switch-hook. A call to telephone A⁴, the telephone number of which is 22531, will be effected in a generally like manner. It will be noted that the telephones A' and A⁴ are located tributary to the "3" and "2" office districts, respectively, while the telephone A (No. 42211) is tributary to the "4" office district, reached by the connector D and other connectors of its group.

Setting the set relay C individual to the line leading to telephone A so if any call is directed to line No. 42211 the call will be forwarded to telephone A⁴ which is No. 22531 tributary to a different central office of the exchange

The party at telephone A will remove his receiver as if to initiate a call, wherein the line switch B will select the first idle first selector E. The party will then operate his calling device dial in accordance with the special setting finger-hold in order to effect a series of eleven open impulses. This will cause the first selector E to operate the eleventh-vertical off-normal spring set 201. Ground will thereupon be applied over conductor 202 to bank terminal 20 of the group 20 to 23, wiper 25 of the group 25 to 28, armature 29, conductor 30, spring 31 on relay C, armature 32 to the winding of relay 33, the latter said relay actuating.

A locking circuit can now be traced through armature 35 to conductor 30 to sustain relay 33 actuated so long as ground exists on conductor 30. The armature 36 disconnects the winding of relay 37. Armature 39 (which makes last) closes an energizing circuit for operating the magnet 40 of relay C. The armature 42 will be locked in its operated position by the dog 43. It will be noted in this connection that when the spring 31 flexes into engagement with its make contact the armature 36 has already attracted to disconnect the winding of relay 37.

At the time relay 33 actuated to energize the magnet 40, armature 45 will have closed a circuit from the tone source 'T' to the lower line conductor leading to telephone A to indicate by specific tone to the party holding the receiver at telephone A that the relay C has operated to set the corresponding line leading from telephone A so that calls there-

- after directed to said line will be forwarded to telephone A⁴ in accordance with the jumpers run from the armatures of relay 802 of the group 801 to 803, as will appear presently.
- 5 The shaft of first selector E will, responsive to the actuation of its switching relay 205, restore to normal position, removing the stated ground from conductor 30 and thereby unlocking relay 33 consistent with the slow-releasing properties of relays 206 and 207.
- 10 The tone applied from source T' to telephone A will then cease and the party at telephone A may then hang up his receiver, leaving the contact springs on relay C operated.
- 15 *Unsetting the set relay C*
- If it is now assumed that the party at telephone A desires to unset the relay C, he having returned to his telephone after an absence, perhaps, he will remove his receiver
- 20 and operate his calling device dial in the manner as when he caused relay C to be set, whereupon the first selector E will operate the off-normal springs set 201 to apply a ground over conductor 30 as before. In view
- 25 of the spring 31 being at this time flexed against its make contact, disengaged from its resting contact, the ground on conductor 30 will be applied through armature 36 to the
- 30 winding of relay 37, the latter said relay operatively energizing and locking through its armature 46 to grounded conductor 30. The armature 32 disconnects the winding of relay 33. Armature 48 (which makes last)
- 35 closes an energizing circuit of magnet 49 for operating the dog 43 for unlatching armature 42 so that said armature 42 will retract. It will be noted, in this connection, that when the spring 31 flexes back to normal position
- 40 into engagement with its resting contact as drawn, responsive to the unlatching of the armature 42, the armature 32 has already attracted to disconnect the winding of relay 33.
- At the time relay 37 actuated to energize
- 45 the magnet 49, armature 50 will close a circuit from the tone source T' to the lower line conductor leading to telephone A to indicate by specific tone to the party holding the receiver at telephone A that the relay C has deactuated to restore the line leading to telephone A to normal, unset condition.
- The shaft of first selector E will restore to normal position and ground will be thereby removed from conductor 30 in a brief time
- 55 after the conductor 30 is caused to be grounded, in the manner as when the relay C was set.
- Making a call from telephone A² to the telephone line leading to telephone A under the condition that the set relay C is set*
- 60 The wipers 51 to 53 of connector D will now be assumed as set upon the bank terminals 55 to 57, respectively, corresponding to line telephone number 42211 leading to telephone A, responsive to the party at telephone
- A⁴ operating the calling dial in accordance with telephone number 42211.
- When the connector D seizes, ground potential is applied therefrom through its wiper 51, bank terminal 55, conductor 59, spring 60, conductor 61, armature 301, lower winding of relay 302 to the winding of common relay 303. Relay 303 will actuate and operatively energize common relay 304. Armature 305 on relay 302 will be attracted from its resting contact into engagement with its make contact. The armature 301 on relay 302 remains inert at this time.
- In this connection, it will be understood that for each line equipped with a set relay like C there will be a specific line relay individual thereto corresponding to relay 302. Also, there will be a set of bank terminals accessible from the finder switch wipers 310 to 313 corresponding to each said line relay. So that when relay 304 actuates the private bank terminal corresponding to 307 for relays corresponding to 302 of all idle said line relays will constitute ground potential. Under the present assumed condition the armature 305 on relay 302 is attracted from its resting contact, so that its private bank terminal 307 (and multiples) will be free of ground potential. That is to say, when relay 304 actuates all private bank terminals accessible from switch F of idle lines (and busy lines due to the busy condition) excepting only the private bank terminal of the line having its line relay in calling condition will be guarded against seizure. Thus, when the line relay 302 attracted its armature 305 from its resting contact to its make contact, the line 42211 seized by connector D is the only line unbarred, subject to seizure by the switch F or a switch of its group.
- At the time relay 304 actuated it applied ground potential over common conductor 314, armature 315 to the winding of slow-releasing relay 316, the latter said relay actuating. Ground received from guarded private bank terminals is applied through wiper 310, armatures 318 and 319, interrupter armature 320 to the interrupter magnet 321, the latter said magnet driving the wipers 310 to 313 until the wiper 310 fails to receive ground. This will be when it reaches bank terminal 307 of the line being called through connector D. The ground applied through armatures 318 and 319 to the upper terminal of the winding of switching relay 325 while wiper 310 was moving over grounded bank terminals will thus be removed so that the relay 325 will operatively energize from ground applied through armature 322 in series with the interrupter magnet 321, also termed motor magnet.
- Relay 316 in switch F being slow-releasing, it remains actuated for an appreciable time after the relay 325 actuates. That is, ground applied through armature 322 will

- be applied through armature 318, wiper 310, bank terminal 307, armature 305, upper winding of relay 302 to grounded battery to fully operate the relay 302 wherein the armature 301 thereof will attract from its resting contact to its make contact. Remembering that the conductor 61 receives ground from the connector D, it will be clear that this ground is applied through wiper 310 to sustain relay 325 before the armature 322 has had time to retract. This ground received over conductor 61 also energizes the upper winding of relay 302 to sustain the latter said relay fully actuated. When relay 316 deactuates the conductor 314 will be thus continued through armature 326 to conductor 327 and to armature corresponding to 315 of the next switch of the group (not shown), so that the said next switch will operate if a new call is initiated before the switch F is returned to idleness.

At this time ground applied through wiper 310 is further applied through attracted armature 329, conductor 330, armature 331 to the winding of relay 332, the latter said relay actuating. Ground is now applied through armature 335, wiper 313, bank terminal 336, conductor 337 to the winding of relay 802. It will be noted in this connection that the relay 802 is individual to the line 42211 seized by connector D, there being as many relays corresponding to 802 as there are lines served by the finder switch F.

Also, ground is now applied through ar-
35 mature 340, conductor 341, wiper 808 (of
group 805 to 808), bank terminal 809, con-
ductor 810, bank terminal 812, wipers 816
and 815 (of group 815 to 818), bank terminal
819, conductor 820, armature 343, conductor
40 345 to the winding of relay 823, the latter
said relay actuating, a locking circuit being
closed through its armature 824, conductor
825, armature 346 to ground. However, the
latter said locking circuit is to no operative
45 purpose until the traced primary energizing
circuit is opened by the wipers 815 and 816
moving off the bank terminals they are shown
resting upon, as will appear presently.

50 At the time relay 332 actuated it closed an energizing circuit from the upper winding of relay 401, armature 402, conductor 403, armature 347, conductor 828, armatures 829 and 830 in multiple, conductor 831, armature 348, conductor 349, armature 404 to the lower winding of relay 401, the latter said relay actuating, followed by dependent slow-releasing relay 405.

The ground interrupter I⁸ revolves continuously at the rate of approximately twelve revolutions per second, so that the first ground application to conductor 832 following the actuation of relay 823 will be applied through armatures 833 and 834 to the winding of impulse sending relay 835, the latter said relay thus attracting its armature 830

from its resting contact in accordance with the operation of the interrupter I^s. The armature 838 is in multiple with armature 834, so that the ground applications effective to relay 835 will be coincidentally effective to the motor magnet 839 to cause the wipers 815 to 818 to be successively advanced in unison with the operation of relay 835.

When the wiper 817 engages bank terminal 840 ground is applied from said terminal, armature 841 to the winding of relay 842, the latter said relay actuating to remove the short circuit through the armature 829 so that the armature 830 will send open impulses effective to the line relay 401 in first selector G. 75 80

At this time it will be noted that the terminals X on the relay 802, counting from left to right, correspond to the numerically progressive ranks of series of a train of five series of open impulses constituting the digits of the number of the telephone line 22531, wherein the terminals Y directly below the relay 802 determine the number of open impulses in the individual series of the train in correspondence with the jumpers joining the X terminals with a respective Y terminals. The sets of terminals Y refer to digit series from 1 to 0, counting from the left, and therefore refer to the terminals swept by wiper 815, counting from the right starting with bank terminal 845. 95 90 95 85

A circuit can now be traced from ground, armature 340, conductor 341, wiper 808, bank terminal 809, armature 846, jumper 847 to 100 the terminal Y corresponding to bank terminal 848 which determines digit 2.

As the wipers 815 to 818 progress, responsive to impulses from the interrupter I⁸, wherein the relay 842 energized at the time wiper 817 reaches bank terminal 840, it will be clear that, for each successive bank terminal position following 840 reached in the advancement of the wipers, one open impulse will be transmitted by the armature 830 of relay 835 to the line relay 401. However, since bank terminal 848 constitutes ground poten- 105 110

115
120
125
130

initial, when the motor magnet deenergizes the second time after the wiper 817 is set upon the bank terminal 840, the wiper 815 will receive ground from bank terminal 848 and apply it through wiper 816, conductor 850 to the winding of slow-releasing relay 851, the latter said relay actuating and locking through its armature 841, wiper 817 to ground on the engaged bank terminal. Relays 835 and 842 are deenergized and maintained so. This locking ground is also applied through armature 852 to the resting contact of the interrupter armature 853, so that while the relay 851 is locked, ground is applied to cause the interrupter magnet 839 to operate to restore the wipers 815 and 817 to the drawn position, at which time the said locking ground received through wiper 817

at off-normal positions is opened. Relay 851 then deactuates consistent with its slow-releasing characteristic.

At the time relay 851 actuated the armature 854 applied ground to the winding of the motor magnet 855. When the relay 851 deactuated the wipers 805 to 808 were caused to advance one step due to the deenergization of the magnet 855.

10 When the relay 851 deactuated the circuits thereupon became in condition for driving the wipers 815 to 818 as before. However, since the wiper 808 is now resting upon bank terminal 856 the ground on wiper 808 is applied through armature 857 on relay 802, jumper 858 to the terminal Y corresponding to bank terminal 848 which again determines digit 2.

20 The armature 830 of relay 835 will send two open impulses as before, this time being effective to set the second selector B⁴ in the well known manner to select the third selector C⁴.

25 It is thought that the foregoing explanation will make clear the subsequent operations wherein the wiper 808 advances one step following each digit series until the remaining three digits 5-3-1, which are determined by the jumpers 859, 860 and 861, are sent. The wiper 806 will thereafter step to bank terminal 862 where it will receive ground from conductor 345. The said digits 5-3-1 will cause the third selector C⁴ to select the connector D⁴ and then set the connector D⁴ into connection with the line leading to telephone A⁴, the connector automatically applying signaling current to operate the bell of the telephone, in the well known manner.

40 The ground received by wiper 806 following the sending of the last impulse of the last series of the train of series will be applied over conductor 865, make-before-break spring 350 to the winding of relay 351, the latter said relay actuating and locking by armature 331 to grounded conductor 330. The attraction of armature 331 deenergizes relay 332, so that the windings of the line relay of the connector D⁴ are now energized 50 in series with make-before-break springs 355-356, armatures 357-358 and the winding of the polarized relay 360 in series, the direction of current traversing the latter said relay being such that its armature 361 will tilt clockwise into the designated "Ring. pos.". Slow-releasing relay 365 will actuate to close a temporary circuit from the make contact of retracted armature 367 to attracted armature 368.

60 *Party at telephone A⁴ responds*

Upon the party at telephone A⁴ removing his receiver in responding, the connector D⁴ will operate in the well known manner to 65 disconnect the signaling current and reverse

the direction of current projected through the windings of polarized relay 360 from the line relay of said connector. This will cause the armature 361 to tilt counter-clockwise into the indicated "Ans. pos.", whereupon the relay 370 will operatively energize and by its armature 367 close a conductive path through armature 372 and the back-bridge relay of the connector D. This will cause the direction of current in telephone A² to be reversed from the line relay in connector D. When the armature 372 on the relay 365 retracts, consistent with its slow-releasing characteristic, the short-circuit through the make-before-break spring 374 will be opened and the calling telephone A² and the finally called telephone A⁴ will be in talking relation over the heavy conductors including conductors 62 and 63, wherein the condensers 376 and 377 are interposed and the winding of polarized relay 360 is in bridge of the talking conductors towards the finally called telephone A⁴, and the retardation coil 378 will be in bridge of the talking conductors towards the calling telephone A².

90 *Calling party hangs up receiver first*

If it is assumed that the calling party at telephone A² hangs up first after the conversation has terminated, it will be noted that the connector D will remain in seizure while the antecedent selectors and line switch will restore, there being no change in the circuits beyond the connector D in the direction of the telephone A⁴.

100 *Called party hangs up receiver first*

If it is assumed that the called party at telephone A⁴ hangs up first after the conversation has terminated, it will be noted that the direction of current traversing the winding of relay 360 will be reversed so that relay 370 will deactuate and relay 365 will actuate. This opens the circuit path energizing the back-bridge relay in the connector D and reverses the direction of current traversing telephone A², the connector D remaining in seizure. The winding of the relay 360 being in series with the line relay of the connector D⁴, the latter said connector will remain in seizure with the line leading to telephone A⁴. When the calling party replaces his receiver at telephone A² the connector D will restore, followed by the antecedent switches. Ground will thus be removed from conductor 330, causing relay 351 to deactuate to open the path including the winding of relay 360 so that the connector D⁴ and antecedent switches will restore, relays 325 and 302 also deactuating at this time.

110 *Calling party at telephone A² abandons call before forwarding has been completed to telephone A⁴*

If it is assumed that while the described call was being forwarded towards the tele-

phone A⁴ the calling party abandoned the call by hanging up the receiver at telephone A², it will be noted that the connector D and the antecedent switches will thereupon restore. This will cause relays 325, 302 and 332 to deactivate so that the switches beyond switch F in the direction of the telephone A⁴ will restore. Relays 802 and 823 in the impulse sending mechanism Fig. 8, will deactivate. Regardless of the off-normal position of the set of wipers 805 to 808 and the set of wipers 815 to 818, the retraction of the armatures 866 and 867 will cause the restoration of the said wipers by causing the interrupter actions of the motor magnets 855 and 839. However, it will be noted that since the connector D restored, the line leading to telephone A is thereupon unguarded and subject to new seizure even though the latter said wiper sets have not had time to restore before a new seizure occurs. It will be further noted that unless the said wiper sets are at normal position ground cannot be applied over conductor 820, armature 343, conductor 345 to the winding of relay 823. That is, the impulsing through the armature 833 cannot be initiated unless the switches N and O have their wipers at the normal, drawn position, in condition to start transmitting an impulse series train. The relay 823 will actuate if the line leading to telephone A is prematurely seized only after the switches N and O have thereafter restored their respective wipers to normal position.

35 *Call to telephone A under condition of relay C being in normal, unset condition*

Under the condition of the connector seizing the terminals of the line leading to telephone A under the condition that the relay C is unset, the ground applied from the connector through the wiper 51, bank terminal 55, conductor 65 operates the line-cut-off relay 66, in the well known manner, so that the line conductors leading to telephone A will be disconnected from the line relay 69 and the ground on resting contact of armature 68. The connector D will thereupon apply ringing current to operate the bell at telephone A.

55 *Party at telephone A may, after causing the set relay to be set for forwarding calls, test the set-up arrangement*

The party at telephone A may at any time after hanging up his receiver after causing the set relay C to become set, again remove his receiver and call the number of his own telephone line, whereupon the call will be forwarded to the line prearranged by the set condition of the relay C, as if the call had been made by a random other subscriber of the exchange. This will verify to the party at telephone A that the set condition is as intended. The calling party may then in-

form the responding party that the calls to the calling party's line will be forwarded to the line of the responding party.

5 *Call to line corresponding to relay 803 in Fig. 8*

If it is assumed that the connector D, or a random connector, is set upon the terminals of the line (not shown) which corresponds to relay 803, the finder switch F will seize the set of bank terminals upon which the wipers 310 to 313 are shown resting, the line relay corresponding to relay 302 therefore not being shown. Under the last said assumed condition the impulse sending mechanism in Fig. 8 will send a train of impulse series corresponding to telephone number 34341, being the line leading to telephone A'. 75 80

85 *Call to line corresponding to relay 801 in Fig. 8—Prolonging space between first and second digit series*

If it is assumed that the connector D, or a random connector, is set upon the terminals of the line which corresponds to relay 801, 90 and therefore the finder switch F will seize the set of bank terminals on the left, the line relay corresponding to 302 therefore not being shown. Under the last said assumed condition, the impulse sending mechanism will send a train of impulse series corresponding to telephone number 11111, which is the operator's answering jack 600 in Fig. 6, accessible from connector J, and other connectors of its group. That is, the selector G, secondary line switch SL⁴, selectors H and I will operate in the well known manner responsive to the first three series of one impulse each, and the connector J will step its wipers up one and in one to the position corresponding to jack 600. 95 100 105

In view of the secondary trunk line switch SL⁴, provided for the outgoing first level trunk from selector G to the incoming second selector H, an additional trunk hunting time must be provided in order to not unduly delay calls not progressed through secondary trunk line switches. The present invention provides for lengthening the hunting space between the first and second digit series for calls routed through the secondary trunk line switch SL⁴ and selector H. This is accomplished through the agency of the armature 870 on relay 801 and the switch arm 871, together with the slow-releasing relay 872. 110 115 120

At the termination of the first impulse series, being one impulse in the present instance, the relay 851 will actuate, grounded battery being applied through armature 875, winding of relay 872, bank terminal 876, wiper 805, armature 870, switch arm 871, armature 877, conductor 810, bank terminal 809, wiper 808, conductor 341, armature 340 to ground. The relay 872 will actuate under the condition and remain actuated consistent with its slow-re- 125 130

leasing characteristic until after the relay 851 deactuates and the wiper 805 has thereupon advanced off bank terminal 876. During the time the relay 872 is actuated its armature 880 disables the application of impulses from interrupter I⁶ through the armature 833, and this correspondingly delays the starting of the second impulse series of the train in order to permit the predetermined time for the 5 trunk hunting by the first selector G and the trunk line secondary switch SL⁴. In this connection, it will be noted that the wiper 805 is specific to effecting the said delay only between the first and second impulse series. 10 However, if the conductor connected to bank terminal 876 is detached and attached to a random other bank terminal co-operative with the wiper 805 the delay will occur following the series sent while the wiper is resting on the said random bank terminal. 15

It will be noted that the armature 870 may be in multiple with corresponding armatures on other relays for routing calls through the 20 group of secondary switches of which SL⁴ is one. That is, these armatures corresponding to 870 are individual to the wiper 805.

In case it is desired to make the specific prolonged trunk hunting delay between other 25 digit series of trains, it will be necessary to provide a wiper for switch N specific to the 30 location of delay desired, the bank terminal 876 being multiplied with such bank terminal or terminals, respectively, swept by the said provided wiper or wipers, having in mind 35 that only one of the wipers for operating relay 872 will be effectively operative at a time.

Operation of the connector J and other equipment at the attendant's switchboard

40 The attendant's switchboard may be located at any point in the telephone system. That is, it may be in one of the exchange offices and attended by an operator employed by the exchange operating concern, or it may be located at some other point attended by a private operator whose office is to act as responding secretary for a number of subscribers of the system located at random in the exchange.

45 It will be clear that the jacks shown accessible from the connector J may be in the same building with said connector and all at the same attendant's switchboard, or these jacks may be located at considerable distance 55 and at various points; that is, responded to by a number of different operators in different parts of the exchange area. Moreover, where the said jack is located some distance from the connector, it will be preferable to 60 use a two-conductor line with a relay and lamp for a calling signal, in place of a directly connected lamp calling signal.

At the time the connector J is seized by the selector I the windings of the line relay 601 65 become in series with the conductors 348 and

831 leading to armatures 829 and 830 in multiple of the impulse sending mechanism in Fig. 8. Slow-releasing release relay 602 will thereupon actuate, causing ground applied through make-before-break spring 603 to be further applied through armature 604 to the release trunk 605. The connector J is now ready to receive the last two digit impulse series "1—1" of the train, in order to set the wipers 607 to 610 upon the bank terminals 611 to 614, respectively, corresponding to jack 600 and its companion calling lamp 617. 70

The next to last open impulse series of one impulse sent by the armature 830 in Fig. 8 will cause the armature 618 to momentarily retract to apply ground through armature 619, off-normal springs 620 and 621, winding of series slow-releasing relay 622 to the winding of the vertical magnet designated "Vert. M." This will cause the shaft carrying wipers 607 to 610 to be raised one step into alignment with the first level of bank terminals, the relay 622 actuating and then de-actuating consistent with its slow-releasing characteristic. If a plurality of impulses had been sent in place of a single one, the armature of relay 622 would sustain attracted until after the last impulse of the series were sent. When the shaft stepped off-normal the spring 621 is thereby disengaged from spring 620, and the latter said spring becomes engaged with spring 623. 85

The last impulse series of one impulse causes the armature 618 to momentarily apply ground through armature 619, springs 620 and 623, armatures 624, 625 and 626 to the winding of the rotary magnet designated "Rot. M." the said magnet operating one time to rotate the shaft carrying wipers 607 to 610 to set said wipers on the first set of bank terminals 611 to 614, respectively, corresponding to jack 600. The winding of the slow-releasing rotary relay 627 is in multiple with the winding of the rotary magnet and actuates with the rotary magnet. If a plurality of impulses had been sent to the rotary magnet and relay 627, in place of a single impulse, the armatures of relay 627 would sustain attracted until after the last 90 impulse of the series is sent. 100

If it is assumed that the line leading to jack 600 is idle, and therefore the bank terminal 612 constitutes battery potential derived through the resistor 629, this battery will be applied through armature 630, lower winding of wiper closing relay 631, armature 632 to the grounded conductor 605, the relay 631 actuating so that its upper winding will lock through armature 634 to the said conductor 605. Under the present condition the ringing current source G⁶ produces no effect. However, ground from conductor 605 110

is applied through armatures 636 and 637, wiper 607, bank terminal 611 to the lamp 115 120 125 130

617, the said lamp glowing to indicate a call to its companion jack 600.

Responsive to the glowing of lamp 617 the attendant will insert answering plug 639 shown in Fig. 6A into the jack 600. This will complete a conductive circuit path from the generator G² (or the negative battery), armature 640, upper winding of relay 641, armatures 642 and 643, wiper 609, bank terminal 10 613, tip spring of jack 600, plug and operator's telephone circuit, sleeve spring of jack 600, bank terminal 614, wiper 610, armatures 645 and 646 to ground, the relay 641 actuating and locking by its lower winding to the conductor 605. Plug 639 also busy-grounds terminal 612.

The back-bridge relay 647 will now actuate, energized through the operator's telephone circuit, and by its inside armatures cause the 20 direction of current derived from the windings of the line relay 601 to be reversed effective to the polarized relay 360 in Fig. 3, remembering that following the last open impulse sent by armature 830 the relay 351 in 25 Fig. 3 will actuate and relay 332 therein will deactivate.

The calling party at telephone A² is now in talking relation over the heavy conductors with the attendant operator's telephone circuit through the jack 600 in Fig. 6.

Restoration of connector J

The shaft of connector J may now be restored to normal by either of two methods. 35 First, by the calling party at telephone A² abandoning the call and thereby opening the energizing path for the windings of relay 601 at armatures 357 and 358. This will cause relays 601 and 602 to deactivate and close the 40 obvious circuit for the release magnet designated "Rel. M.", which will restore the shaft of connector J to normal, together with antecedent switches. Second, by the operator withdrawing the plug 639 from the jack 600. 45 The latter is in view of the fact that when the back-bridge relay 647 actuated, it operatively energized the upper winding of relay 649, the latter said relay locking by its lower winding to conductor 605. When the plug 639 is 50 withdrawn the relay 647 deactuates, armature 650 applying its ground through armature 652 over an obvious path to the release magnet, causing the shaft of connector J to restore.

55 It will be noted, in this connection, that when relay 647 actuated, ground was applied through armature 655 to armature 656 so that when the relay 649 thereafter actuated the ground applied to the conductor 605 is derived 60 through armatures 655 and 656 in place of as originally through the make-before-break spring 603. Thus, at the same time that relay 647 deactuates responsive to withdrawing the plug 639, ground will be removed from conductor 605 to cause the relay 631 (and inci-

dentially relay 641) to deactivate, so that the wipers 607 to 610 will be dead when retracting over bank terminals. The object of releasing the connector J responsive to withdrawing the plug 639 will appear presently. 70

Operation of connector J in the event the bank terminal 612 constituted busy ground when the connector tested same

It will now be assumed that at the time 75 the connector J set its wipers on the bank terminals corresponding to jack 600 the bank terminal 612 constituted busy ground, due to another connector of the group (not shown) being in seizure of the said jack. Under this 80 assumed condition there will be no battery to energize the lower winding of relay 631, so that talking connection will be barred to the selected said jack. Also, before the relay 627 had time to retract its armatures, consistent with its slow-releasing characteristic, the ground encountered on bank terminal 612 will be applied through wiper 608, armature 630, make-before-break spring 660, armature 661 to the winding of busy relay 662, the 90 latter said relay actuating. A locking circuit for relay 662 is completed through make-before-break spring 663, armature 632 to conductor 605. The busy tone source T² is now applied through armatures 665 and 666 to 95 the upper talking conductor, audible to the calling party by way of armature 372 in Fig. 3.

Calling lamp for attendant's answering jack 100 re-glow when a call is made while said jack is busy in a previous call to indicate that there is a waiting call

Notwithstanding that the lamp 617 extinguished responsive to the answering of the 105 call existing, and which latter call causes the present assumed busy condition, this lamp will be caused to re-glow as a calling signal due to ground being applied from the conductor corresponding to 605 in the connector 110 encountering the busy condition. This ground on conductor corresponding to 605 will be applied through armatures of the latter said connector corresponding to 636 and 637, and through wiper corresponding to 607 115 to bank terminal in multiple with bank terminal 611 and to the lamp 617, as if the assumed busy condition did not exist.

It will also be clear that if another connector is now set upon bank terminals corresponding to the jack 600, the calling party concerned in that call will also be apprised by busy tone from source T². Further, that the latter said connector will also apply ground to bank terminal in multiple with bank terminal 611, so that even if the connector first barred due to the busy condition is caused to seize responsive to the attendant momentarily withdrawing her plug 639 to thereby disconnect the connector causing the 120 125 130

busy condition, the lamp 617 will still glow due to the second connector (and perhaps also a subsequent connector selecting the jack 600) receiving the busy condition, as will appear presently.

10 Connectors encountering a busy condition wherein more than one said connector receives the busy condition when attempting to connect with the same jack will be enabled to seize said jack automatically only in the order in which they were set upon the terminals corresponding to the jack

15 At the time the connector J was assumed to encounter the jack 600 as busy and the relay 662 locked and applied a busy tone audible to the calling party, armature 667 applied its ground through winding of relay 668 to conductor 669, and armature 670 applied its ground through armatures 671 and 672 to common start conductor 673. This ground on conductor 673 is applied through armature 701 in switch K in Fig. 7 to the winding of slow-releasing relay 702, the latter said relay actuating.

20 Before proceeding with the description of the operation of the switch K, it is pointed out that there are as many sets of bank terminals commonly accessible from the set of 30 wipers on the right in each of the switches K, L and M as there are connectors as J embraced thereby. That is, the switches K, L and M, and other switches of the group not shown, may embrace connectors in a plurality of groups reached from various levels of the selector I, each group serving one hundred answering jacks on the attendant's switchboard.

25 It will be further noted that the bar conductor 703 (individual to connector J) is normally grounded through armature 667, and since the latter said armature may be attracted while the connector wipers are rotating over busy bank terminals while being 35 driven to the desired bank terminal, and under which condition the relay 627 is actuated wherein its armature 628 then maintains the continuity of the circuit to the rotary magnet, the armature 670 will serve to maintain 40 ground on bar conductor 703. That is, that the bar conductor 703 will be maintained grounded under all conditions excepting when the busy relay 662 is locked because of a busy condition, having in mind that even 45 after the busy relay 662 locks the ground will not be removed from conductor 703 until after the armature 670 has had time to retract. So that it will be further noted that the start conductor 673 will not be grounded 50 from connector J until after armature 670 removes the ground from the bar conductor 703.

55 When the busy relay 662 actuates and locks, due to the connector J encountering the selected jack 600 as busy, it will thereupon cause

the common start conductor 673 to become grounded and remove the ground from the bar conductor 703 individual to the connector J. The relay 702 of switch K will actuate if the latter said switch is idle, and if it (K) is busy, the corresponding relay on the first idle switch as L or M will actuate over the chained continuation of the conductor 673.

60 It will be assumed for the present that all bar conductors other than 703 are grounded, indicating that no other said embraced connector has its busy relay corresponding to 65 662 locked. Therefore, the wiper 706 of the group 704 to 706 will be resting upon a grounded random bank terminal under this assumed condition. The armature 713 of relay 702 will apply ground to the lower winding terminal of relay 707. The ground derived through wiper 706 will be applied 70 through armatures 708 and 709 to the upper winding terminal of relay 707, thus short-circuiting said winding while the latter said ground is also applied through the interrupter armature and winding of motor magnet 710. The motor magnet now operates to 75 successively advance the set of wipers 704 to 706 as long as wiper 706 finds ground potential on the bank terminal it is resting upon.

80 However, ground was assumed removed from bar conductor 703, so that when wiper 706 is set upon bank terminal 711 there will be no direct ground potential applied through armature 709 to maintain the operation of the motor magnet 710 and the short-circuit 85 on the winding of relay 707. Under this condition the ground applied through armature 713 is applied through the windings of relay 707 and the motor magnet 710 in series, the relay 707 actuating while the motor magnet 90 remains inert due to its marginal adjustment. This disconnects the winding of relay 702 and it deactuates. The conductor 669 constitutes ground potential received from armature 667, so that when the relay 707 actuates 95 this ground is applied through wiper 705, armature 712 to the lower winding terminal of relay 707 before the armature 713 on relay 702 has had time to retract, so that relay 707 is maintained actuated. Also, ground will be applied through armature 708 and wiper 706 100 to bank terminal 711 to place bar ground on conductor 703. That is, the relay 707 is now maintained actuated dependent upon the attracted condition of armature 667, and this condition also maintains bar conductor 703 105 grounded. Series relay 668 is operatively energized in series with the winding of relay 707, and by attracting its armature 672 disconnects ground applied from armature 670, from common start conductor 673.

110 Grounded armature 715 operatively energizes relay 716. Grounded battery 717 is applied through a resistor, conductor 718, bank terminal 719, wiper 722 of the set 720 to 723, armature 725 winding of relay 726 115 120

to ground, the latter said relay actuating. In this connection, it will be noted that current from battery 717 is also being applied through a resistor, conductor 727, bank terminals 728 and 729, wiper 721, armature 730, winding of said relay 726 to ground.

Ground from armature 732 operatively energizes the motor magnet 733, so that the motor magnet successively drives the set of wipers 720 to 723 forward. When wiper 723 engages the second bank terminal 724 it will receive battery potential through a resistor which is further applied through the winding of relay 726 to ground. The motor magnet, under the condition will continue to drive the wipers until the wiper 721 engages grounded bank terminal 735 whereupon the winding of relay 726 is short-circuited by the latter said ground and it deactuates to disable the motor magnet 733. The winding of relay 726 is high so that it will derive but small current and its armature 732 will not be appreciably retarded in retracting.

At this time the said ground from bank terminal 735 is also applied through armature 725, wiper 722 to bank terminal 736.

The grounded shaft 739 is driven by a motor or other mover in the direction indicated by the arrow at approximately one revolution per second, although the rate of revolution is of secondary importance and is chosen in view of various conditions. This shaft 739 is shown with seven circuit grounding cams or commutators 740 to 746. While the light conductive portion of the respective cams pass the respective indicated contact brushes 740' to 746' the corresponding conductors 740'' to 746'' attached to the said brushes will constitute ground potential.

Remembering the set condition of the two wiper sets of the switch K, it will be assumed that another connector (not shown) embraced by the switches K, L and M is operated into selective relation with the bank terminals corresponding to the jack 600, and thereupon operates its busy relay corresponding to 662 responsive to the busy condition encountered, which will cause the common start conductor 673 to become again grounded. In view of the attracted condition of armature 701 this ground will be continued through armatures 750 and 751 to the winding of slow-releasing relay 752, the latter said relay actuating. Since the switch L is like switch K, its operation in hunting for the ungrounded bar bank terminal (not shown) which attaches to the bar conductor corresponding to 703 individual to the latter concerned connector not shown, the operation will be clear without more detailed description. When the said ungrounded bar bank terminal is found and the relay 753 actuates and the relay 752 thereupon deactuates, the armature 755 thereupon operatively energizes the relay 756.

A circuit path can now be traced from bat-

tery source 717, resistor, conductor 718, bank terminal 757, wiper 760 of set 758 to 761, armature 762, winding of relay 763 to ground, the latter said relay actuating. Armature 764 will apply its ground through the interrupter armature to the winding of motor magnet 765 to cause the set of wipers 758 to 761 to progressively advance.

Returning to the condition which ensued after wiper 721 of switch K reached grounded bank terminal 735 and remembering that relay 716 is actuated, it will be clear that this ground applied to wiper 721 will be continued through armatures 730 and 725, wiper 722 to bank terminals 736 and 766 and conductor 767. Therefore, when the wiper 759 of switch L encounters bank terminal 768 it will receive ground potential received over the traced path from bank terminal 735. This ground potential will be applied through armature 769 to the upper winding terminal of relay 763, causing the latter said relay to deactuate and stop the operation of the motor magnet 765.

The ground potential on bank terminal 768 is applied through wiper 759, armatures 769 and 762, wiper 760 to bank terminal 770 and conductor 771, the relay 756 remaining actuated.

Remembering the set condition of the two wiper sets in switch K, and the set condition of the two wiper sets in switch L, it will be assumed that another connector (not shown) embraced by the switches K, L and M is operated into selective relation with the bank terminals corresponding to the jack 600 and thereupon operates its busy relay corresponding to 662 responsive to the busy condition encountered, which will cause the common start conductor 673 to become again grounded. In view of the attracted condition of armatures 701 and 751 this ground will be continued through armatures 772 and 773 to the winding of slow-releasing relay 774, the latter said relay actuating. Since the switch M is like switches K and L, its operation in hunting for the ungrounded bar bank terminal (not shown) which attaches to the bar conductor corresponding to 703 individual to the last said concerned connector, will be clear without more detailed description. When the said ungrounded bar bank terminal is found and the relay 775 actuates and the relay 774 thereupon deactuates, the armature 776 thereupon operatively energizes the relay 777.

A circuit path can now be traced from battery source 717, resistor, conductor 718, bank terminal 778, wiper 781 of set 779 to 782, armature 783, winding of relay 784 to ground, the latter said relay actuating. Armature 785 will apply its ground through the interrupter armature to the winding of the motor magnet 786 to cause the set of wipers 779 to 782 to progressively advance.

Remembering that after wiper 759 of switch L reached grounded bank terminal 768, bank terminal 770, conductor 771 and bank terminals 787 and 788 constituted ground potential, it will be clear that when the wiper 780 of switch M reaches bank terminal 788 this ground will short-circuit the winding of relay 784 and cause the armature 785 to retract to stop the operation of the 10 motor magnet 786. Wiper 781 now rests upon bank terminal 789. Under the latter condition ground potential on bank terminal 788 is applied through wiper 780, armatures 790 and 783, wiper 781, bank terminal 789 to 15 conductor 791.

In a commercial embodiment of the present invention there would be as many switches K, L and M successively subject to being chained by the continuations of the start conductor 673 as there would probably be connectors, as J, in selective relation with bank terminals encountered busy and wherein the busy relay as 662 is locked actuated.

In view of foregoing descriptions it will 25 be clear that responsive to the actuation of the seizing relay as 707, 753 and 775 the corresponding motor magnet 733, 765 and 786 will set its corresponding wiper set one bank terminal set position antecedent to the wiper 30 position of the last switch operated.

Assuming the switches K, L and M set in the positions described in the foregoing, it will be clear that every time the conducting segment of the commutator 740 passes the 35 brush 740' ground will be applied to conductor 740'' and over the obvious multiplied circuit paths to the respective windings of the relays 792, 793 and 794 to grounded battery, the said relays actuating and locking over 40 conductor 741'', brush 741', conductive segment of commutator 741 to ground. Also, that when the conductive segment of commutator 741 passes from under brush 741' this locking ground on conductor 741'' will be 45 disconnected so that the said relays 792, 793 and 794 will deactivate, remembering that briefly after the conductive segment of commutator 740 applied ground to brush 740' it disconnected it, while the commutator 741 50 thereafter applied locking ground through brush 741' to conductor 741''.

It will now be clear that only after a relay as 726, 763 and 784 has deactivated, while respectively corresponding relays 716, 756 and 55 777 are actuated, will it be possible to energize the corresponding relay as 792, 793 and 794. This thus means that unless a switch, as K, L and M, has its left-hand set of wipers in set and seized condition with respect 60 to a set of bank terminals, the corresponding relay 792, 793 and 794 cannot be energized.

The commutators 742 to 746 will apply ground to brushes 742' to 746' and conductors 742'' to 746'' in numerically successive 65 order. It will be clear that unless the wipers

as 720, 758 and 779 are operative due to the closed condition of the upper armatures on the relays 792 to 794 this grounding of said conductors can be to no effective purpose although the said wipers may be resting on a 70 bank terminal attached to a said conductor.

Having in mind the assumed relative positions of the said wipers wherein wiper 720 is resting on bank terminal 795 attached to conductor 742''; wiper 758 is resting on bank terminal 796 attached to conductor 743''; and wiper 779 is resting on bank terminal 997 attached to conductor 744'', it will be clear that the impulses applied to the conductors 742'' to 744'' will be in numerical succession in correspondence with the order in which the switches K, L and M were set. That is, ground impulses will be applied in succession through the upper armatures of relays 792 to 794 in the numerical succession indicative of the order the switches containing the latter said relays were set. 80

It will be noted that when a ground impulse is applied through the upper armature of relay 792, armature of relay 707, wiper 704, bank terminal 798, conductor 799 to the winding of relay 675, the latter said relay will actuate. Armature 676 will flex the make-before-break spring 663 so that the relay 662 is no longer locked to grounded conductor 605, but on the other hand, the locking circuit for relay 662 is now applied through armature 676, wiper 608 to private bank terminal 612. If the latter said terminal constitutes ground potential due to the fact that it is busy guarded by a connector in seizure with jack 600, this ground will serve to maintain the relay 662 locked until the momentary ground is removed from conductor 799 and the armature 676 thereupon retracts to restore the locking circuit for relay 662 to the grounded conductor 605. 90

However, had the bank terminal 612 constituted battery potential, indicative of an idle condition of the jack 600, there would be no locking ground to maintain the relay 662 actuated when armature 676 flexed spring 663 from its resting contact, and it would retract its armatures. This would complete an energizing circuit from battery on said bank terminal 612, wiper 608, armature 630, lower winding of relay 631, armature 632 to grounded conductor 605, the relay 631 actuating and locking by its upper winding and armature 634 to conductor 605, thus effecting the seizure of the terminals leading to the jack 600. 100

In this connection, it will be noted that the unbusying of the jack 600 may have resulted from the calling party hanging up his receiver, causing the connector J to restore, or it may have resulted from the operator withdrawing her connecting plug 639, causing the connector J to restore. 110

When the relay 662 deactuates it removes 125

ground from the conductor 669 individual to connector J and at the same time places bar ground on conductor 703 individual to connector J, so when armature 708 in switch K 5 retracts responsive to the ground being removed from conductor 669 the connector J will be barred against any switch as K, L and M, and the switch K will return to normal condition subject to new use with any 10 connector embraced by it. In this connection, it will be noted that responsive to the deactuation of relay 707 the relay 716 will deactuate. This will cause battery applied through a resistor to be further applied 15 through wiper 723, lower armature of relay 716, winding or relay 726 to ground, the latter said relay actuating to start the interrupter operation of the motor magnet 733 to restore the wipers 720 to 723 to the drawn 20 position.

Remembering that the switches K, L and M seized in the order written, it will be clear that the relays corresponding to 675 of the co-operated connectors will be caused to momentarily 25 actuate in the same order so that the first connector to receive the busy condition will be the first one enabled to seize the jack 600 when it becomes idle.

At the time relay 716 in switch K deactuates, wipers 721 and 722 cease to apply ground received from bank terminal 735 to bank terminal 766, conductor 767 and attached bank terminals. Under the latter condition, ground applied from conductor 767, 30 through bank terminal 768, wiper 759, armatures 769 and 762, wiper 760, bank terminal 770 to conductor 771 will be changed to battery potential derived through a resistor. This battery potential will operatively energize 35 relay 763 to cause the motor magnet 765 to operate to advance the wipers 759 and 760 until wiper 759 encounters the indicated permanent ground on the left-hand bank terminal next following 768, whereupon the winding 40 of relay 763 will be short-circuited and the armature 764 will retract to disable the motor magnet 765. Wiper 758 is now resting on the bank terminal next following 796, corresponding to conductor 742". The latter conductor, 45 it will be remember, is grounded first after the conductor 740". That is, the connector co-operated with the switch L now has the first order of access to the jack 600.

In the same manner as just described, the 50 conductor 791 and attached bank terminals will be ungrounded, so that the switch M will advance its wipers 779 to 782 to the second bank terminal set counting from the left, and accordingly the wiper 779 becomes in engagement with a bank terminal attached to conductor 743". That is, the connector co-operated with the switch M, now has the second order of access to the jack 600.

If it is now assumed that another connector 55 (not shown) embraced by the switches K, L

and M, encounters the jack 600 busy, the start conductors 673 will become grounded and the bar conductor corresponding to the concerned connector will become ungrounded. The switch K will operate as before described to 70 find the concerned connector, and then the left-hand wipers will be operated until wiper 721 encounters a grounded bank terminal, which, under the present assumed condition, will be on the third bank terminal counting 75 from the left, so that the wiper 720 is in communication with conductor 744". That is, the connector co-operated with switch K has the third order of access to the jack 600.

Party encountering a busy condition and given an order of access abandons call 80

Had the calling party concerned in any of the calls abandoned his call after attaining an order of access through the agency of one of the switches K, L or M, the concerned switch will restore responsive to the co-operated connector restoring, whereupon the holding conductor corresponding to 669 will become ungrounded to cause the corresponding switch 90 K, L or M to restore as if the connector had seized, in place of restoring. Any other switch or switches K, L or M having subsequent order of access will advance to take the order or orders vacated. 95

In this connection, it will be noted that had the busy encountered call through connector J in the first assumed condition been abandoned, restoring the switch K to idleness, both the switches L and M would function exactly like described, when it was assumed the connector J seized. In view of the fact that the wipers 759 and 779 of both switches L and M become ungrounded at the same time there might be a chance for a delay in grounding 100 by the advance switch so that the rear switch would not be restrained at its proper bank position, and therefore rotate over all succeeding positions and return to normal. To guard against this remote possibility, if adjustments become upset, the resistors associated with the battery 717 are graded in value 105 so that the advance switch will receive a stronger current for more quickly energizing its relay as 763, and thus insure that its motor magnet will at least not be started after the rear positioned switch has started. 110

Order of access given all connectors encountering a busy condition regardless of the fact they may not have called the same jack 115 120

In the foregoing descriptions, the connectors were assumed to have encountered the busy condition while seeking connection with the jack 600. The same operation as described would ensue had the connectors each been in selective relation to a different busy jack. However, the delay which may be occasioned in seizing a line after it becomes idle will not exceed the time of the revolution 125 130

of the shaft 739. That is, the relay corresponding to 675 of each said connector will be momentarily operated approximately once every second to test the selected line 5 for idleness.

Tone applied momentarily to selected busy jack so that the users thereof will hasten the release of it

- 10 Each time the testing relay, as 675, is momentarily operated, tone from source TT⁶ is applied through armature, as 678, to the lower talking conductor leading from armature, as 645, to apprise the parties on the 15 busy line the wiper, as 610, is connected with through its bank terminal, as 614. This occurs in like manner in each connector in selective relation to a busy line.
- 20 *Momentary interruption of busy tone to indicate to waiting calling party that he is not locked-on-busy, but on the other hand has an order of access to the line encountered busy*
- 25

In this connection, it will be noted that each time relay, as 675, actuates to retest the terminals of the jack encountered busy, its lower armature, as 666, will momentarily dispel the busy tone T⁶ with respect to the concerned connector, so that the interruptions to the busy tone will indicate to the concerned party calling that he has an order of access, 30 and that the busy tone is not the usual permanently locked-on-busy condition obtained when calling a busy normal subscriber's telephone line.

- 40 *Tone from source T⁶ may simulate the generator reverting ringing tone so that the calling party will believe the connector is applying ringing current to an idle called line and will not abandon the call which will be responded to shortly, since the connector is not permanently barred from seizing the jack*
- 45

The tone source T⁶ may be derived from the generator G⁶ through armature, as 640, so 50 that the tone of said generator will be heard by the calling party under the order of access busy condition. This will indicate simply delay in the response, in place of the positive 55 and permanent bar against completing the ensuing connection, as is generally understood from the high-pitched busy tone.

Of course, the busy tone applied audible to the calling party may be dispensed with, 60 since the attendant is apprised of the new call by the glowing of the call lamp and the apprising tone applied from the source TT⁶, and that the call will be responded to by the attendant very shortly. In this case, the tone 65 source T⁶ would be dispensed with.

Attendant may take on waiting successive calls to a busy jack as fast as desired

In view of the foregoing, it will be clear that if the attendant hears the busy tone 70 from the source TT⁶ and notices the glowing of the lamp 617 while she is talking with a calling party, she may hasten the termination of the call and then withdraw her answering plug, and thereby release the connector through which she talked, whereupon the connector having the next order of access will be caused to seize in accordance with the operation of the commutators on the shaft 739. The lamp 617 will extinguish 75 forthwith upon the next connector seizing when the operator re-inserts her answering plug 639, only provided there is not then another connector awaiting access to the said jack, because the lamp 617 would be energized from any and all waiting connectors.

It will be understood that where the attendant's jack, as 600, is to be located at some distance from the connectors, it will be objectionable to run a conductor to the lamp, 80 as 617. Under this condition, the direct lamp 617 will be displaced by any well known or suitable bridged signal having a condenser in series therewith, as shown in Fig. 16. Under this condition, the source G⁶ will 85 apply ringing current to operate the signal device, and this current will be cut off when the attendant inserts her answering plug 639. If there are waiting connectors, the signal device will not operate while the plug 130 is inserted in the jack, but as soon as the plug is removed to cause the connector to restore, or the calling party abandons the call causing the connector to restore, the waiting connector having the first order of access will 135 seize and the ringing current will be applied therefrom to operate the signal device at the jack as a new calling signal.

Preferred modification of Fig. 6 shown in Fig. 17 prevents more than one set of bank terminals accessible from the switches K, L and M being subject to seizure at a time to make the order of access positively in accordance with the order of encountering the busy condition

It will appear from the foregoing descriptions that it is possible for two connectors embraced by the switches K, L and M to encounter a busy condition at or nearly the same time, under which condition, there may be two or more bar terminals unbarred accessible from a hunting one of said switches. In order to preclude this condition, the preferred modification shown in Fig. 17 will be 125 described.

It will be noted that the modification concerns the conductors 669, 673 and 703, and armatures 667, 670 and 671. The relay 680 is added common to all the connectors embraced 130

by switches K, L and M. The relay 681 is individual to the connector J having relay 668.

- When armatures 667 and 671 attract and 5 armature 670 retracts responsive to the concerned connector J encountering a busy condition, relay 681 will be operatively energized in series with armatures 682 and 672 and the start conductor 673. This will cause 10 the common relay 680 to be operatively energized from armature 683. There is an armature 682 and an armature 684 on the relay 680 individual to each connector embraced by the switches K, L and M. Armature 685 attracts to disable ground being applied from armature 684 to bar conductor 703. Armature 686 attracts into engagement with its make contact before armature 682 attracts from its resting contact so that the circuit 20 continuity between the armature 671 and conductor 673 is not opened. However, it will appear that if any other associated connector encounters a busy condition, due to the actuated condition of relay 680, the relay of the 25 latter said connector, corresponding to 681, will be disabled from being energized so that ground will be applied through the armature corresponding to 685 of the latter said relay to the bar conductor corresponding to 30 703 individual to the latter said connector. This will prevent the switch K, L or M from seizing the latter said connector, and enable it to seize only the connector J which first encountered the busy condition.
- 35 When the connector J has been found by the switch K, L or M and ground is thereupon derived through the winding of relay 668, the armature 672 will attract to deenergize relay 681, under which latter condition the relay 680 will be deenergized. This 40 will close a circuit path from the armature 671 through the armature on relay 680 corresponding to 682, so that the relay corresponding to 681 will be energized in series 45 with the start conductor 673. The common relay 680 will thereupon reactuate to place a ground on all bar conductors corresponding to 703 excepting the one individual to the connector last encountering a busy condition.
- 50 In case there are more than one connector that has encountered a busy condition waiting its turn to be found by one of the switches K, L or M while one of the latter said switches is hunting for a connector which previously encountered a busy condition, when 55 the latter said connector is found and its relay corresponding to 681 deenergizes, all the relays corresponding to this latter relay 60 associated with the said waiting connectors will actuate so that all said connectors will be subject to being connected to by a said switch K, L or M since their respective bar conductors corresponding to 703 will be free 65 of ground simultaneously.

Preferred method of changing the telephone number call is to be sent to under directive control of the impulse sending mechanism

With reference to Fig. 8, the descriptions set forth that temporary jumpers were run 70 from the terminals X of relay 802 to numeral terminals Y. It will be understood that a subscriber using the call forwarding service may, from time to time, desire to 75 change the destination of calls forwarded from his line, or perhaps a said subscriber discontinues the service and it is then desired to employ the call forwarding apparatus with some other line.

The preferred arrangement disclosed in 80 Figs. 13 and 14 is for the purpose of obviating the said jumpers, and to readily change the predetermined destination of forwarded calls. The switch-arms 880 to 884 will be 85 attached to the X terminals 885 to 889 in place of the jumpers shown in Fig. 8. In place of the set of Y terminals for each relay 801 to 803 there will be terminals adapted to be 90 swept by said switch-arms 880 to 884. So that the central office attendant may, in place of running jumpers, simply set the said switch-arms in correspondence with the desired forwarded connection, telephone number 58512 in the exemplified instance.

95 Fig. 13 shows one of the said switch-arms 880, all said switch-arms 880 to 884, being alike. The switch-arm 880 is made of metal simulating the form of a wiper on the well known rotary line switches referred to at the outset. The switch-arm 880 is mounted on 100 an insulating member 890 which fits revolvably on a fixed spindle 891. The outer end of the switch-arm 880 sweeps bank terminals 892. So that the switch-arms 880 to 884 simulate in general appearance a five-wiper line switch having ten bank terminals for each wiper. In the periphery of each insulating member as 890 are a number of round holes 893 spaced with the same radial angle as the 105 bank terminals. To set the switch-arms or wipers it is only necessary to manually revolve them about the spindle 891 to the desired location with respect to the bank terminals swept by each. In order to insure 110 that the setting will not be accidentally disturbed, a temporary pin of metal will be inserted through the registering holes 893 of the insulating members of the five wipers 880 to 884, so that the said wipers cannot be 115 revolved about the spindle irrespective of each other. There is a fixed plate with holes spaced to register with the holes in the insulating members, as 890, so that the said pin, not 120 shown, can pass through the registering holes in the five insulating members, as 890, and into the registering hole of the said fixed plate, not shown. This locks the wipers 125 against movement.

Preferred embodiment employing line finder switch Q in Fig. 9, and associated figures in place of line finder switch F in Fig. 3

5 Considering now the preferred embodiment wherein an impulse sending mechanism serves a plurality of finder switches, the figures will be assembled as indicated by the diagram Fig. 18. The general operation of the
 10 system is not changed, so far as the subscribers are concerned, as the modification looks to economy in quantity of equipment to serve a certain traffic.

At the time the conductor 61 is grounded
 15 responsive to the connector D seizing the bank terminals 55 to 57 in Fig. 1, this ground will be applied through armature 901, lower winding of relay 902 to the winding of common relay 903. Relay 903 will actuate and
 20 operatively energize common relay 904. Armature 905 on relay 902 will be attracted from its resting contact into engagement with its make contact. Due to adjustment, armature 901 on relay 902 remains inert at this time.

25 In this connection, it will be understood that there will be a set of bank terminals accessible from the finder switch wipers 908 to 913 corresponding to each line relay as 902. So that when the relay 904 actuates, the private bank terminal corresponding to 907
 30 for the relay corresponding to 902 of all idle said line relays, will constitute ground potential. Under the present assumed condition, the armature 905 on relay 902 is attracted from its resting contact so that its private bank terminal 907 (and multiples) will be free of ground potential. That is to say, when relay 904 actuates, all private bank terminals accessible from switch F of idle
 35 lines (and busy lines due to the busy condition) excepting only the private bank terminal of the line having its line relay in calling condition, will be guarded against seizure. Thus, when the line relay 902 attracted
 40 its armature 905 from its resting contact to its make contact, the line 42211, which was seized by connector D, is the only line subject to seizure by the switch Q or a switch of its group.

50 At the time relay 904 actuated, it applied ground potential over common conductor 914, armature 915 to the winding of slow-releasing relay 916, the latter said relay actuating. Ground received from guarded private bank
 55 terminals is applied through wiper 908, armatures 918 and 919, interrupter armature 920 to the interrupter magnet 921, the latter said magnet driving the wipers 908 to 913 until the wiper 908 fails to receive ground.
 60 This will be when it reaches bank terminal 907 of the line being called through connector D. The ground applied to the upper terminal of the winding of switching relay 925 while wiper 908 was moving over grounded bank terminals will thus be removed so that

the relay 925 will operatively energize in series with the motor magnet 921. The conductor 914 will thus be continued through armature 926 to conductor 927, and to armature corresponding to 915 of the next switch 70 of the group (not shown), so that the said next switch will operate if a new call is initiated (or one is waiting) before the switch Q is returned to idleness.

Relay 916 in switch Q being slow-releasing, it remains actuated for an appreciable time after the relay 925 actuates. That is, ground applied through armature 922 will be applied through armature 918, wiper 908, bank terminal 907, armature 905, upper winding of relay 902 to grounded battery to fully operate the relay 902 wherein the armature 901 thereof will attract from its resting contact to its make contact. Remembering that the conductor 61 receives ground from the connector D, it will be clear that this ground is applied through wiper 908 to sustain relay 925 before the armature 922 has had time to retract. This ground received over conductor 61 also energizes the upper winding of relay 902 to sustain the latter said relay fully actuated. 85 90

At this time ground applied through wiper 908 is further applied through attracted armature 929, conductor 930, armatures 931 and 932, the lower winding of relay 933, winding of common relay 934 to grounded battery. Common relay 935 will operatively energize in a local circuit of relay 934. Armature 936 on relay 933 attracts from its resting contact to its make contact. Due to adjustment, armature 932 on relay 933 remains inert. Armature 937 being attracted, ground is applied over start conductor 938 and to all retracted armatures corresponding to 936 embraced by the common relay 935. So that conductors corresponding to 939 attached to a retracted armature corresponding to 936 will be grounded. However, armature 936 being attracted into engagement with its make contact, the conductor 939 has battery potential derived through the upper winding of relay 933. 100 105 110

Ground on start conductor 938 is applied through armature 101 to the winding of slow-releasing relay 102 in finder switch R in Fig. 10, the latter said relay actuating. The wipers 103 to 108 of said switch R will be resting upon a random set of bank terminals since they have no normal restored position. Therefore, the wiper 104 will be resting upon a bank terminal having ground potential, since it extends over a common conductor corresponding to 939 to an armature corresponding to 936 of some relay other than 933. If the said other relay is idle, the said conductor, as 939, will receive ground from common armature 937. If the said relay is fully actuated it will be grounded from conductor, as 930, by way of retracted armature, 115 120 125 130

as 931, and attracted armature, as 932. Thus, the relay 933 having only its armature 936 attracted from its resting contact into engagement with its make contact renders conductor 939 ungrounded; in fact applied to battery through the upper winding of relay 933.

Armature 110 applies ground to the lower winding terminal of relay 112, and ground 10 received through bank terminal 113 is applied through wiper 104, armatures 114 and 115 to the upper winding terminal of relay 112 to short-circuit the latter said relay and apply direct ground through the interrupter armature of motor magnet 116 to the winding thereof, the motor magnet operating to drive the set of wipers forward. When the wiper 104 reaches bank terminal 117, which attaches to common conductor 939, there will be no 20 ground to maintain the short-circuit to the upper winding terminal of relay 112. The relay 112 will actuate under the condition, its winding in series with the winding of the motor magnet 116, the latter being adjusted 25 to remain inert under the condition of the winding of relay 112 being in series with it.

In view of the slow-releasing characteristic of relay 102, the armature 110 will sustain attracted to apply ground through armature 30 114, wiper 104, bank terminal 117, conductor 939, armature 936, upper winding of relay 933 to battery, the latter said relay fully actuating. Under the latter condition ground is applied from conductor 930, armatures 931 35 and 932 and its make contact to conductor 939, bank terminal 117, wiper 104, armature 114 to the lower winding terminal of relay 112 to sustain it before the armature 110 has had time to retract. The ground applied 40 through the wiper 104 will also be applied through the armature 118, wiper 105, bank terminal 119, common conductor 120, armature 941 to the winding of relay 942, the latter said relay actuating.

45 A circuit can now be traced from battery, upper winding of relay 401 in first selector G, armature 402, conductor 403, conductor 943, armature 944, common conductor 945, bank terminal 122, wiper 107, armature 123, conductor 124, conductor 348, armatures 829 and 830 in multiple, conductor 831, conductor 125, wiper 108, bank terminal 126, common conductor 127, armature 946, conductor 947, conductor 349, armature 405, lower winding 50 of relay 401 to ground, the latter said relay actuating. Armature 128 applies ground over conductor 129, conductor 341 to wiper 808.

55 Armature 130 closes a path involving conductors 131, 132, 820 and 345, causing relay 823 to operatively energize from ground applied by armature 128 through wiper 808. Ground is applied through armature 134, conductors 135 and 825 to armature 824 to 60 complete a locking circuit for the winding of

relay 823. Ground is applied through armature 136, wiper 103, bank terminal 137, common conductor 138, wiper 911, bank terminal 950, conductors 951 and 337 to the winding of relay 802, the latter said relay actuating.

It is thought, in view of previous descriptions with relation to Fig. 8 when co-operated with Figs. 3 and 4, that the operation of the impulse sending mechanism shown in Fig. 8 in operating the first selector G and succeeding switches in completing a connection to telephone A⁴, number 22531, will be clear and therefore need not be repeated. However, in the present instance, when the wiper 806 encounters ground on bank terminal 862, this 70 ground will be applied over conductors 865 and 140, wiper 106, bank terminal 141, common conductor 142, make-before-break spring 953 to the winding of relay 954, the latter said relay actuating. This deenergizes relay 85 942 and removes the ground applied through armature 932 for sustaining relay 933 fully actuated, and also applied over conductor 939 to sustain relay 112 in switch R actuated. Relays 942, 933 and 112 therefore deactuate. The switch R and its companion impulse sending mechanism in Fig. 8 are now idle, subject to new use as before, having in mind that since relay 933 is now deactuated should a call be initiated on another line embraced by the common relays 934 and 935 wherein the latter two relays will actuate, armature 937 will apply ground through armature 936, conductor 939 to bank terminal 117 to bar the switch R against seizing the finder switch Q while it is still in use in the call. So that while the wipers of the finder switch R remain on the bank terminals corresponding to finder switch Q, they are all dead due to the retracted condition of the 100 armatures on relays 102 and 112. When relay 102 is again caused to actuate, while switch Q is still in service in the ensuing call the wipers of switch R will rotate off in hunting operation for a finder switch of the group 105 containing switch Q, as when the bank terminal 113 was assumed grounded when the ensuing call was completed by connector D to the terminals of the line leading to telephone A.

110 Going back to the condition in switch Q when the relay 954 actuated and the relay 942 deactuated, it will appear that the windings of the line relay 401 in connector D⁴ will now be included with armatures 956— 115 957 and the winding of polarized relay 960. The direction of current projected back from the line relay in the connector D⁴ will be such that the armature of the relay 960 will tilt clockwise into the designated "Ring. pos.", 120 under which condition the slow-releasing relay 962 will be operatively energized. When the party at telephone A⁴ responds to the call the direction of current traversing the winding of relay 960 will be reversed, tilting 125 130

its armature into the designated "Ans. pos.", whereupon relay 963 will actuate and relay 962 will deactuate consistent with its slow-releasing characteristic.

- 5 After relay 963 actuates, and before relay 962 deactuates, a conductive circuit for energizing the back-bridge relay in connector D is closed which includes wipers 52-53, bank terminals 56-57, conductors 62-63, conductors 10 965-966, bank terminals 967-968, wipers 909-910, armatures 969-970, armatures 971 and 972. The said back-bridge relay in connector D will thus actuate to reverse the direction of current traversing the telephone 15 A². The calling party at telephone A² will now be in talking relation with the party at telephone A⁴ over the heavy conductors. When the armature 971 retracts, armature 972 being attracted, the retardation coil 973 is in 20 series with the back-bridge relay in connector D.

It will be obvious that the restoration of the switches and apparatus involved in linking the call will occur responsive to the parties 25 to the call hanging up, in the general manner as described when the finder switch F was interposed, in place of the present finder switch Q.

With reference to Figs. 11 and 12, which 30 show finder switches S and T belonging to the same group with finder switch R. It will be understood that an impulse sending mechanism like that shown in Fig. 8 will be individual to each Fig. 11 and Fig. 12, but 35 are not shown.

When the impulse sending mechanism cooperative with Fig. 10 is operating, the start conductor 938 is chained through armatures 101 and 160, conductor 161, armature 162 in 40 switch S of Fig. 11, to the winding of slow-releasing relay 163. Thus, if a new call is initiated to a line relay corresponding to 902 in Fig. 9 and one of the finder switches (not shown) of the group containing switch Q operates to seize the corresponding line the start conductor 938 will become grounded. Under the latter condition the relay 163 in switch S will actuate to cause the switch S to hunt for and seize the concerned said finder switch 45 of the group containing switch Q.

It will be noted, in this connection, that the finder switches R, S and T accessible to the group of finder switches containing switch Q have individual wipers as 911, 912 55 and 913 on the latter said finder switches. That is to say, the upper wiper, as 911, in each switch of the said group of switches are individual to the finder switch R; the middle wiper as 912 in each switch of the said group 60 are individual to the finder switch S; the lower wiper as 913 in each switch of the said group of switches are individual to finder switch T. Thus, the three wipers 911 to 913 65 are individual to the relays corresponding to 801 to 803 in each of the three impulse send-

ing mechanisms respectively companion to the finder switches R, S and T in Figs. 10, 11 and 12. This also applies to each switch of the group containing switch Q.

In view of the foregoing, it will be clear 70 that when the finder switches R and S are both in seizure, the start conductor 938 will be further chained from armature 162 through armature 164, conductor 165, armature 166 in switch T to slow-releasing relay 167. Also, when the finder switches R, S and T are all in seizure, the start conductor 939 will be further chained from armature 166, armature 168 to conductor 169. The present embodiment thus provides for three sending 75 mechanisms operating simultaneously wherein as soon as a train of impulses has been sent the concerned finder switch R, S and T and its companion sending mechanism is subject to use in a new call while the last 80 extended call may not yet be responded to.

It will be understood that the individual 85 impulse sending mechanisms companion to the finder switches R, S and T will be identical with each other and that the group of 90 relays as 801 to 803 (and others not shown) in each said mechanism will be connected and jumpered similarly for all said relay groups, so that regardless of which said mechanism is concerned, calls to a random set line will be 95 forwarded in one predetermined manner to a corresponding predetermined line.

Preferred modification of Figs. 1, 9, 10, 11 and 12

Fig. 15 shows portions of Figs. 1, 9, 10, 11 and 12, into which are introduced the following modifications.

Applying signaling current to the primarily called line

The winding of added relay 175 is in series 100 with conductor 61, so that when the connector D applies ground to bank terminal 55, said relay 175 will actuate to apply the generator G' in bridge of the conductors of the 105 line leading to telephone A, while armature 176 applies ground to the private conductor 65 to operate the line-cut-off relay 66 in line switch B so that the ringing current from the 110 said source G' will not affect the line relay 69 in the line switch B. The bell at telephone 115 A will thus be rung with a distinctive character of current only until the line finder switch as Q finds the terminals corresponding 120 to the relay 902, and the relay 175 has had time to deactuate. This brief ringing of the bell will remind the party at telephone A, if he 125 is there, that he failed to unset the relay C. He can now intercept the call by removing his receiver and then sending the series of eleven open impulses to unset the relay C.

When relay 902 fully operates responsive to the finder switch seizing the corresponding bank terminals, the winding of relay 175 will 130

be short-circuited by armature 177. Under the latter condition there will be no current derived through the winding of relay 175, so that it will deactivate consistent with its 5 slow-releasing characteristic introduced by reason of the short-circuit on the winding.

Preventing the disablement of a finder switch in case an antecedent finder switch becomes idle

- 10 With reference to the modification of finder switches R, S and T to embody changes to prevent disablement of a finder switch which has operated responsive to the grounding of 15 the start conductor 938, in the event the chain to the said finder switch then operating is opened by reason of an antecedent switch of the group restoring to idle condition. Only such parts of said switches are shown in Fig. 20 15 as will be necessary to comprehensively disclose the modifications.

Assume that none of the switches R, S and T are in use when the start conductor 938 becomes grounded in the manner explained. 25 This ground will be applied through armature 180, make-before-break spring 181, armature 101 to the winding of relay 102. Armature 182 applies ground through armature 183 to the winding of added relay 184, 30 the latter said relay actuating. Armature 185 flexes spring 181 out of engagement with its resting contact and applies the ground on start conductor 938 through armature 101 to maintain relay 102 energized. Ground from 35 conductor 938 is also applied through said armature 185, spring 184 to the winding of common relay 186. Armature 180 on relay 186 attracts to disable the application of ground from start conductor 938 through 40 armature 180 while any other relay 187 or 188 is actuated, regardless of the fact that switch R may have become idle in the meantime.

If it is assumed that the switches R and S 45 are in use and the start conductor 938 which was ungrounded becomes grounded, this ground will be applied through armature 180, spring 181, armature 101, armature 160, conductor 161, spring 189, armatures 162 and 50 164, conductor 165, spring 190, armature 166 to the winding of relay 167, the latter said relay actuating. Armature 191 will apply ground through armature 192 to the winding of relay 188, the latter said relay actuating. 55 Ground on the start conductor 938 will now be applied through armature 193, spring 190, armature 166 to maintain the winding of relay 167 energized so the switch T will continue to hunt.

60 If it is now assumed that while the switch T is hunting the switch R or S returns to idleness and thereby opens the traced chain ground to conductor 165 the relay 167 will not be affected because it is deriving current 65 direct from start conductor 938 through the

spring 190. Since relay 186 is operatively energized due to the attracted condition of armature 193, there will be no way to re-energize relay 102 or relay 163 from ground on the start conductor 938 until relay 186 restores, and the latter cannot occur as long as relay 188 is actuated, which condition will endure until armature 192 attracts, or that the armature 191 retracts due to the call being abandoned.

Busy tone is applied audible to the calling party when all finder switches of either group are busy

The relay 902, and other similar relays of its group, each have an added armature 194, shown in Fig. 15, and co-operating make-before-break spring 195 and resting contact therefor. The armature 194 is so tensioned that it will engage the spring 195 but not flex it from its resting contact responsive to the energization of the lower winding of relay 902 wherein armature 901 does not operate. However, at the time the upper winding of the relay 902 energizes to operatively attract the armature 901, the armature 194 will flex spring 195 from its resting contact.

The added relay 196 has its winding connected to the conductor 927, which is the extension of the start conductor 914, and also to the conductor 169 which latter is the extension of start conductor 938. In other words, when all the finder switches in the group containing switch Q are in use, the conductor 927 (or an extension thereof) has the start ground thereon, provided there is a call awaiting a finder switch of the latter said group. Also, that when all the switches R, S and T are in use, the extension 169 of the start conductor 938 has the start ground thereon provided there is a finder switch of the group containing Q in seizure with a set line called and there is no idle switch R, S or T for co-operation therewith. Thus, when all finder switches of either or both said groups are in use and there is a demand for a finder switch in one of the groups, the relay 196 will actuate to apply busy tone from source T¹⁵ through armature 194 to the talking conductor 966, audible to the calling party at telephone A², assuming, for example, that the demand is occasioned by a call from telephone A² to the line leading to telephone A, wherein the relay C is set.

It is to be understood that the details disclosed in Figs. 13, 14, 15 and 17 are not merely alternative structures of modifications, but on the contrary, are to be understood as belonging to the structure to which they refer; that is, as elements of the main embodiments first described to which they relate. These elements disclosed in part in Figs. 13, 14, 15 and 17 have been so illustrated separately solely to simplify the disclosure as a whole

of which they are to be considered a component part.

I claim:—

1. In an automatic telephone system, a plurality of subscribers' lines, a set mechanism for each of said lines, other lines, a calling line, first switch mechanism for linking connection from the calling line to a random one of said subscribers' lines, second switch mechanism for linking connection from the subscribers' lines to said other lines, a cooperating switch mechanism, an impulse sending mechanism, means operated over a random one of said subscribers' lines for permanently operating its corresponding set mechanism, means responsive to linking connection from the calling line to the said random line only under the condition that the set mechanism thereof is operated for causing said cooperating switch mechanism to cooperate said impulse sending mechanism with the connection, means operated responsive to said cooperation for thereupon operating the impulse sending mechanism to send impulses to direct the forwarding of the connection from the particular one of said subscribers' lines connected with by said second switch mechanism to a specific one of said other lines depending upon the one of said subscribers' lines connected with, to thereby complete a connection from the calling line to one of said other lines corresponding to said random one of said subscribers' lines wherein the terminals of the latter said line connected with are included in the connection.

2. In an automatic telephone system, a plurality of subscribers' lines, a set mechanism for each of said lines, other lines, a calling line, first switch mechanism for linking connection from the calling line to a random one of said subscribers' lines, second switch mechanism for linking connection from the subscribers' lines to said other lines, a cooperating switch mechanism, an impulse sending mechanism, means operated over a random one of said subscribers' lines for permanently operating its corresponding set mechanism, means operated over the latter said line for effacing the operated state of said set mechanism, means responsive to linking connection from the calling line to the said random line only under the condition that the set mechanism thereof is operated for causing said cooperating switch mechanism to cooperate said impulse sending mechanism with the connection, means operated responsive to said cooperation for thereupon operating the impulse sending mechanism to send impulses to direct the forwarding of the connection from the particular one of said subscribers' lines connected with by said second switch mechanism to a specific one of said other lines depending upon the one of said subscribers' lines connected with, to thereby complete a connection from the calling line

3. In an automatic telephone system, a plurality of subscribers' lines, a set mechanism for each of said lines, other lines, a calling line, first switch mechanism for linking connection from the calling line to a random one of said subscribers' lines, second switch mechanism for linking connection from the subscribers' lines to said other lines, a finder switch, an impulse sending mechanism, means operated over a random one of said subscribers' lines for permanently operating its corresponding set mechanism, means responsive to linking connection from the calling line to the said random line only under the condition that the set mechanism thereof is operated for causing said finder switch to cooperate said impulse sending mechanism with the connection, means operated responsive to said cooperation for thereupon operating the impulse sending mechanism to send impulses to direct the forwarding of the connection from the particular one of said subscribers' lines connected with by said second switch mechanism to a specific one of said other lines depending upon the one of said subscribers' lines connected with, to thereby complete a connection from the calling line to one of said other lines corresponding to said random one of said subscribers' lines wherein the connection includes a portion of the latter said line as a link.

4. In an automatic telephone system, a plurality of subscribers' lines, a set mechanism for each of said lines, other lines, a calling line, first switch mechanism for linking connection from the calling line to a random one of said subscribers' lines, second switch mechanism for linking connection from the subscribers' lines to said other lines, a group of finder switches, impulse sending mechanisms, means operated over a random one of said subscribers' lines for permanently operating its corresponding set mechanism, means responsive to linking connection from the calling line to the said random line only under the condition that the set mechanism thereof is operated for causing a random one of said finder switches to cooperate said connection and one of said sending mechanisms, means operated responsive to said cooperation for thereupon operating the impulse sending mechanism to send impulses to direct the forwarding of the connection from the particular one of said subscribers' lines connected with by said second switch mechanism to a specific one of said other lines depending upon the one of said subscribers' lines connected with, to thereby complete a connection from the calling line to one of said other lines corresponding to said random one of said subscribers' lines wherein the connection includes a portion of the latter said line as a link.

includes a portion of the latter said line as a link.

5. In an automatic telephone system, a plurality of subscribers' lines, a set mechanism for each said line, other lines, a calling line, first switch mechanism for linking connection from the calling line to a random one of said subscribers' lines, second switch mechanism for linking connection from the subscribers' lines to said other lines, a group of finder switches, a group of impulse sending mechanisms, means operated over a random one of said subscribers' lines for permanently operating its corresponding set mechanism, means responsive to linking connection from the calling line to the said random line only under the condition that the set mechanism thereof is operated for causing a random one of said finder switches to select said random line, means also responsive to linking said connection for causing a random one of said sending mechanisms to become cooperated with said connection, means operated responsive to last said cooperation for thereupon operating the impulse sending mechanism to send impulses to direct the forwarding of the connection from the one of said random subscribers' lines connected with by said first switch mechanism to a specific one of said other lines depending upon the one of said subscribers' lines that is said random line, to thereby complete a connection from the calling line to one of said other lines corresponding to said random one of said subscribers' lines wherein the connection includes a portion of the latter said line as a link.

6. In an automatic telephone system, a plurality of subscribers' lines, a set mechanism for each said line, other lines, a calling line, first switch mechanism for linking connection from the calling line to a random one of said subscribers' lines, second switch mechanism for linking connection from the subscribers' lines to said other lines, a first group of finder switches, a second group of finder switches, a group of impulse sending mechanisms wherein each said sending mechanism is permanently companion to a respective finder switch of said second group of finder switches, means operated over a random one of said subscribers' lines for permanently operating its corresponding set mechanism, means responsive to linking connection from the calling line to the said random line only under the condition that the set mechanism thereof is operated for causing a random one of said first group of finder switches to select said random line, means also responsive to linking said connection for causing a random one of said second group of finder switches to select the finder switch which selected said random line for causing its companion impulse sending mechanism to become cooperated with said connection, means operated responsive to last said cooperation for there-

upon operating the impulse sending mechanism to send impulses to direct the forwarding of the connection from the one of said random subscribers' lines connected with by said first switch mechanism to a specific one of said other lines depending upon the one of said subscribers' lines that is said random line, to thereby complete a connection from the calling line to one of said other lines corresponding to said random one of said subscribers' lines wherein the connection includes a portion of the latter said line as a link.

7. In an automatic telephone system, a plurality of subscribers' lines, other lines, a calling line, first switch mechanism for linking connection from the calling line to a random one of said subscribers' lines, second switch mechanism for linking connection from the subscribers' lines to said other lines, a first group of finder switches, a second group of finder switches, a group of impulse sending mechanisms wherein each said sending mechanism is permanently companion to a respective finder switch of said second group of finder switches, means responsive to linking connection from the calling line to the said random line for causing a random one of said first group of finder switches to select said random line, means also responsive to linking said connection for causing a random one of said second group of finder switches to select the finder switch which selected said random line for causing its companion impulse sending mechanism to become cooperated with said connection, means operated responsive to last said cooperation for thereupon operating the impulse sending mechanism to send impulses to direct the forwarding of the connection from the one of said random subscribers' lines connected with by said first switch mechanism to a specific one of said other lines depending upon the one of said subscribers' lines that is said random line, to thereby complete a connection from the calling line to one of said other lines corresponding to said random one of said subscribers' lines wherein the connection includes a portion of the latter said line as a link.

8. In an automatic telephone system, automatic switch mechanism, an impulse sending device, means for setting up a stored condition in said device, means for directly operating the switch mechanism responsive to sending a train of series of impulses from said sending device due to said stored condition, automatic means for measuring a minimum space between the respective series of impulses of the train, and means including a relay therefor for measuring a said space having additional minimum length between the last impulse of one series and the first impulse of the next successive series regardless of the number of impulses in the first one of said successive series.

9. In an automatic telephone system, auto-

- matic switch mechanism, an impulse sending device, means for setting up a stored condition in said device, means for directly operating the switch mechanism responsive to sending a train of series of impulses from said sending device due to said stored condition, automatic means for measuring a minimum space between the respective series of impulses of the train to permit time for secondary operation of the switch mechanism 5 between the directive series of the train, and means including a relay therefor for measuring a said space having additional minimum length between the last impulse of one series and the first impulse of the next successive 10 series to allow for additional time for completing said secondary operation regardless of the number of impulses in the first one of said successive series.
10. In an automatic telephone system, a group of finder switches, lines commonly accessible from said switches, a chain circuit linked by contacts of certain of said switches due to their unavailable state when busy for 15 predetermining which said switches will be enabled to next operate, means for energizing said chain circuit for causing said predetermined switch to operate to hunt for a random said line responsive to the initiation of a call 20 on the latter said line, means for preventing said predetermined switch from being disabled from said hunting although said chain circuit to said predetermined switch is de- 25 energized by opening the chain circuit at one 30 of said contacts before said line has been found, and means whereby the last said hunting 35 operation is dependent upon the said initiated call being maintained.
11. In an automatic telephone system, a group of finder switches, lines commonly accessible from said switches, normally open contacts of certain of the switches which contacts are closed only if its switch is in its 40 operated condition, a circuit path adapted 45 to be chained through said contacts, means for energizing said chained circuit path responsive to initiating a call on a random one 50 of said lines, means whereby energizing said circuit path will cause only the switch suc- 55 cessive to the last operated switch to be thereby caused to hunt for and seize said random line, means for preventing the disablement of said hunting although said chained circuit is opened at one of said contacts while said circuit path is maintained energized to said 60 opened contact, and means whereby the last 65 said hunting operation is dependent upon the said initiated call being maintained.
12. In an automatic telephone system, a group of finder switches, lines commonly accessible from said switches, normally open contacts of certain of the switches which contacts are closed only if its switch is in its 70 operated condition, a start circuit, a circuit 75 path adapted to the chained from said start circuit through said contacts, means for en- 80 ergizing said start circuit and said chained circuit path responsive to initiating a call on a random one of said lines, means whereby energizing said circuit path will thereby cause only a predetermined switch deter- 85 mined by which said contacts are closed to operate to hunt for and seize said random line, and means for preventing the disablement of said hunting although said chained circuit is opened at one of said contacts while 90 said start circuit is maintained energized.
13. In an automatic telephone system, a group of finder switches, lines commonly accessible from said switches, normally open contacts of certain of the switches which contacts are closed only if its switch is in its operated condition, a start circuit, a circuit path adapted to be chained from said start circuit through said contacts, means for energizing said start circuit and said chained circuit path responsive to initiating a call on a random one of said lines, means whereby energizing said circuit path will thereby cause only a predetermined switch determined by 95 which said contacts are closed to operate to hunt for and seize said random line, and means for preventing a different said switch to start its hunting operation until the switch then hunting seizes an accessible said line or the start circuit has been deenergized, regardless of the fact the said chained path has become open.
14. In an automatic telephone system, a group of finder switches, lines commonly accessible from said switches, normally open contacts of certain of the switches which contacts are closed only if its switch is in its operated condition, a start circuit, a circuit path adapted to be chained from said start circuit through said contacts, means for energizing said start circuit and said chained circuit path responsive to initiating a call on a random one of said lines, means whereby energizing said circuit path will thereby cause only a predetermined switch deter- 100 mined by which said contacts are closed to operate to hunt for and seize said random line, means for preventing a different said switch to start its hunting operation until the switch then hunting seizes an accessible said line or the start circuit has become deenergized, regardless of the fact the said chained path has become open, and a slow-acting 105 means for preventing last said means from becoming disabled although the start circuit has become deenergized until last said deenergized condition has endured a predetermined time so as to prevent disabling said last said means responsive to momentarily deenergizing the start circuit.
15. In an automatic telephone system, a group of finder switches, lines commonly accessible from said switches, normally open contacts of certain of the switches which

- contacts are closed only if its switch is in its operated condition, a start circuit, a circuit path adapted to be chained from said start circuit through said contacts, means for energizing said start circuit and said chained circuit path responsive to initiating a call on a random one of said lines, means whereby energizing said circuit path will thereby cause only a predetermined switch determined by 5 70 which said contacts are closed to operate to hunt for and seize said random line, and means for applying a signal to said random line when all said contacts are closed and said random line has not been seized since 10 75 15 the said call thereon was initiated.
16. In an automatic telephone system, a line, automatic switch means for selecting said line, a second automatic switch means for thereafter selecting said line responsive 20 80 to first said selection, a source of signaling current, automatic means for applying said signaling current to said line responsive to first said selection, and automatic means for disconnecting said signaling current responsive to last said selection of said line. 25 85
17. In an automatic telephone system, an impulse sending mechanism, an interchangeable cross-connecting device comprising a plurality of independently movable wipers 30 90 on a shaft cooperative with an individual set of cross-connecting bank terminals, a first line, a second line, means for setting said wipers in accordance with the designation of said second line, switch means for extending 35 95 connection to said first line, switch means for extending connection from said first line to said second line, means including said cross-connecting device in its set condition operated responsive to effecting connection to 40 100 said first line for causing said impulse sending mechanism to send impulses to directively operate second said switch means to extend connection to said second line, a third line, switch means for extending connection 45 105 from said first line to said third line, and means including said cross-connecting device wherein certain of its wipers are correspondingly set in accordance with the designation of said third line for causing said impulse 50 110 sending device to send impulses to directively operate last said switch means for extending connection from first said line to said third line responsive to connection being extended to said first line.
- 55 115 18. In an automatic telephone system, selective switches, a set of bank terminals of the respective said switches commonly connected to an outgoing answering terminal, means for automatically operating random 60 120 125 130 said switches into connection with its set of commoned terminals, means for making the respective sets of commoned terminals busy by a random one of said switches to bar talking connection to said outgoing answering terminal by said switches other than said random switch although physical connection is made to a set of said terminals connected thereto by each of certain of said switches, and means for preventing a new talking connection from being thereafter established to said outgoing answering terminal excepting in the order in which the busy condition was encountered by the respective switches regardless of the particular said switches concerned. 70 75 80 85 90 95 100 105 110 115 120 125 130
19. In an automatic telephone system, selective switches, a set of bank terminals of the respective said switches commonly connected to an outgoing answering terminal, means for automatically operating random said switches into connection with its set of commoned terminals, means for making the respective sets of commoned terminals busy by a random one of said switches to bar talking connection to said outgoing answering terminal by said switches other than said random switch although physical connection is made to a set of said terminals connected thereto by each of certain of said switches, means for preventing a new talking connection from being thereafter established to said outgoing answering terminal excepting in the order in which the busy condition was encountered by the respective switches regardless of the particular said switches concerned. 80 85 90 95 100 105 110 115 120 125 130
20. In an automatic telephone system, a called line, a plurality of automatic switches for linking a tandem connection to the terminals of the called line, a back release circuit for applying switch sustaining ground back from the last switch linked into the connection, and means controlled over the called line for removing said ground to thereby cause said plurality of switches to restore from the operated condition in the connection. 110 115 120 125 130
21. In an automatic telephone system, a called line, a plurality of automatic switches for linking a tandem connection to the terminals of the called line, means controlled over the calling line for maintaining ground applied back from the last switch linked into the connection to sustain the connection to the said last switch, and means controlled over the called line for removing said ground applied from the said last switch while the connection to said last switch is sustained for 120 125 130

- breaking down the connection to said last switch responsive to the removal of said ground. 22. In a telephone system, a called line, a calling signal individual to the called line, switch mechanism for linking a connection to the called line, means for operating said signal responsive to the extension of said connection, means for manually responding to the call signal and for thereby establishing a talking path over the connection and the called line and for effacing the calling signal, and means for establishing a second similar connection to the called line and reoperating the calling signal while the first talking connection endures without second said extension being placed in talking relation to the first said talking path. 23. In a telephone system, a called line, a calling signal individual to the called line, switch mechanism for linking a connection to the called line, means for operating said signal responsive to the extension of said connection, means for manually responding to the call signal and for thereby establishing a talking path over the connection and the called line and for effacing the calling signal, means for establishing a second similar connection to the called line and for reoperating the calling signal while the first talking connection endures without second said extension being placed in talking relation to the first said talking path, and means controlled over the called line responsive to effacing and then again repeating the manual operation for disconnecting the first said extension to the called line and for again effacing the calling signal and for establishing a talking path over last said extension to the called line. 24. In a telephone system, a called line, a calling signal individual to the called line, switch mechanism for linking a connection to the called line, means for operating said signal responsive to the extension of said connection, means for manually responding to the call signal for thereby effacing the calling signal, means for establishing a second similar connection to the called line and for reoperating the calling signal while the first connection endures without affecting the existing first connection talking path. 25. In an automatic telephone system, connectors each having a locked on busy circuit, means whereby when there is a plurality of said connectors locked on busy in connective relation with a busy called line, but not in seizure thereof, the connectors will be caused to unlock the busy circuit and re-test the called line in connective relation which caused the locked on busy condition to be set up, only in the order in which the connectors encountered the latter said line busy, regardless of which connectors were successively operated into selective relation with said line, and means whereby if the said line is idle when re-tested the connector will seize it. 26. In a telephone system, a called answering outlet, a plurality of automatic switches, means whereby said switches may be successively operated into concurrent connection with said answering outlet wherein but a single one of said operated switches can be in seized relation with said connected with outlet at one time, means for at will breaking down a said seized relation, automatic means for thereupon establishing a new seized relation with the answering outlet by one of said switches concurrently connected with the answering outlet responsive to said breaking down of the seized relation, and means for insuring that the switches concurrently connected with the answering outlet will be enabled to become in seized relation with the answering outlet only in the order in which they became connected with it, regardless of which said switches are operated in succession. 27. In a telephone system, a called answering outlet, a plurality of automatic switches, means whereby said switches may be successively operated into concurrent connection with said answering outlet wherein but a single one of said operated switches can be in seized relation with said connected with outlet at one time, means controlled over the answering outlet for at will breaking down a said seized relation, means controlled over the answering outlet for establishing a new seized relation with the answering outlet by one of said switches concurrently connected with the answering outlet, and means for insuring that the switches concurrently connected with the answering outlet will be enabled to become in seized relation with the answering outlet only in the order in which they became connected with it, regardless of which said switches are operated in succession. 28. In a telephone system, a called answering outlet, a plurality of automatic switches, means whereby said switches may be successively operated into concurrent connection with said answering outlet wherein but a single one of said operated switches can be in talking relation with said connected with outlet at one time, an operator's answering circuit, means operated responsive to the operator connecting her answering circuit to the answering outlet for placing a single one of connected switches in talking relation with the operator's answering circuit, means for disconnecting the operator's answering circuit for disconnecting the switch connected in talking relation to the answering outlet, means responsive to re-connecting the operator's circuit to the answering outlet which will cause another of said connected switches to become in talking relation with the answering outlet, and means for insuring that the

switches connected with the answering outlet will be enabled to become in talking relation with the answering outlet only in the order in which they became connected with it, regardless of which said switches are operated in succession.

29. In a telephone system, a called answering outlet, a plurality of automatic switches, means whereby said switches may be successively operated into concurrent connection with said answering outlet wherein but a single one of said operated switches can be in seized relation with said connected with outlet at one time, a signal device individual to the answering outlet for indicating a connection, means controlled over the answering outlet for effacing the indication of the signal device, means controlled over the answering outlet for at will breaking down a said seized relation with the answering outlet, automatic means responsive to last said operation for thereupon establishing a seized relation with the answering outlet by another one of said switches concurrently connected with the answering outlet, means for insuring that the switches connected with the answering outlet will be enabled to become in seized relation with the answering outlet only in the order in which they became connected to it, regardless of which said switches were operated in succession, and means for causing the signal device to indicate that a waiting switch is connected to the answering outlet while a talking relation exists with respect to a call answered condition.

30. In a telephone system, a called answering outlet, a plurality of automatic switches, means whereby said switches may be successively operated into concurrent connection with said answering outlet wherein but a single one of said operated switches can be in seized relation with said connected with outlet at one time, means controlled over the answering outlet for establishing a talking relation with the answering outlet by the one of said switches connected in seized relation with the answering outlet, means controlled over the answering outlet for breaking down the seized relation of last said switch and for causing another of said connected switches to seize the answering outlet, means controlled over the answering outlet for causing said another switch to become in talking relation with the answering outlet, and means for insuring that the switches connected with the answering outlet will be enabled to become in seized relation with the answering outlet only in the order in which they became connected with it, regardless of which said switches are operated in succession.

31. In a telephone system, a called answering outlet, a plurality of automatic switches, means whereby said switches may be successively operated into concurrent connection with said answering outlet wherein but a sin-

gle one of said operated switches can be in seized relation with said connected with outlet at one time, means controlled over the answering outlet for establishing a talking relation with the answering outlet by the one of said switches connected in seized relation with the answering outlet, means controlled over the answering outlet for breaking down the seized relation of last said switch and for causing another of said connected switches to seize the answering outlet, means controlled over the answering outlet for causing said another switch to become in talking relation with the answering outlet, means for insuring that the switches connected with the answering outlet will be enabled to become in seized relation with the answering outlet only in the order in which they became connected with it, regardless of which said switches are operated in succession, and means operated only by the random one of said switches having the first succeeding order for seizure with the answering outlet with respect to a seized switch with the answering outlet for applying a signal to the connection involving last mentioned switch to indicate that a switch is awaiting to seize the answering outlet when the existing connection thereto in seized relation is broken down.

32. In a telephone system, a called line, a plurality of switches, means whereby said switches may be concurrently connected to said line, means whereby only one of said concurrently connected switches can be in seized relation to the called line at any one time, means whereby as connections are broken down the individual switches will seize the called line only one at a time in the order in which connection by the respective switches was made to the called line, and means for causing only the random one of said connected switches to be enabled to next seize the called line to apply a signal to the called line to indicate the waiting condition of a switch with respect to the called line.

33. In a telephone system, a called answering outlet, a plurality of automatic switches, means whereby said switches may be successively operated into connection with said answering outlet wherein but a single one of said operated switches can be in talking relation with said connected with outlet at one time, means operated over the answering outlet for at will breaking down a said talking relation, automatic means operated over the answering outlet for thereafter at will establishing a talking relation over the answering outlet by one of said switches connected with the answering outlet, and means for insuring that the switches connected with the answering outlet will be enabled to become in talking relation over the answering outlet only in the order in which they became connected with it, regardless of which said switches are operated in succession.

34. In a telephone system, a plurality of switches, a called line having as many sets of incoming terminals as there are switches, a set of movable terminals for each said switch cooperative with a corresponding set of terminals of the called line and individual to the switch, means whereby any said switch can be operated to set its movable terminals on the corresponding fixed terminals of the called line to thereby effect a seized relation from the switch to the called line, means for preventing seized relation from ensuing between a said switch and the called line the fixed terminals of which have the movable terminals of the latter said switch set upon same because of being busy due to another of said switches having its movable terminals beforehand set upon a set of the fixed terminals of the called line, and means whereby switches that have their respective sets of movable terminals set upon fixed terminals of the busy called line will be enabled to become in seized relation with the called line while maintaining the set condition only in the time order in which the movable terminals were set upon the fixed terminals of the called line.

35. In an automatic telephone system, a plurality of switches, a called line accessible commonly from said switches, means for barring more than a single one of said switches from seized relation with said line although all of said switches may be in connection with said line coincidentally, a group of order of access switches common to first said switches, and self-applied automatic means whereby through the agency of said order of access switches each of first said switches gaining connection to the called line will be assigned an order of seizure to the called line in the order in which the first said switches effected connection to the called line without regard to which said switches are operated in succession, and for causing the switches to gain sole seized relation with the called line only in the order in which they gained connection to the called line consistent with the antecedent seized relations being successively terminated or being coincidentally terminated.

36. In an automatic telephone system, a plurality of switches, a called line accessible commonly from said switches, means for barring more than a single random one of said switches from seized relation with said line although all of said switches may be in connection with said line coincidentally, a group of finder switches, means whereby when one of first said switches becomes barred from seized relation with the called line connected to while the called line is in seized relation with another of said switches, one of said finder switches will hunt for and become temporarily individually associated with said barred switch, an order of access switch com-

panion to each said finder switch which will assume a position defining a progressive order of seizure with respect to the called line for the first said switch in said association of the order of access switch with the companion finder switch wherein no two first said switches will have the same order of seizure with respect to the called line, means under the control of each order of access switch when in its said defining state for also defining the position which may be assumed by the next order of access switch to operate, and means for automatically self-adjusting the order of access switches in the event a call is abandoned wherein its corresponding first said switch abandons its order of access so that the remaining order of access switches having successive order of access will assume new advanced orders of access positions to maintain the same mutually relative order of seizure among the barred switches as existed before said abandonment.

37. In a telephone system, a called answering outlet, means for extending connections to said answering outlet wherein a plurality of said connections may exist coincidentally, means whereby more than one said connection to the answering outlet is prevented from being in talking relation at any one time, and means for insuring that the one at a time talking relations to the answering outlet can take place only in the order of effecting the first mentioned connections to the answering outlet, regardless of how many first mentioned connections are in coincident existence to the called answering outlet.

38. In an automatic telephone system, a called answering outlet, automatic switch mechanism for extending connections to said answering outlet wherein a plurality of said connections may exist coincidentally, means whereby more than one said connection to the answering outlet is prevented from being in talking relation at any one time, and means for insuring that the one at a time talking relations to the answering outlet can take place only in the order of effecting the first mentioned connections to the answering outlet, regardless of how many first mentioned connections are in coincident existence to the called answering outlet.

39. In a telephone system, a telephone line, a set relay for said line, means for locking said relay responsive to actuating it, a second relay operated over said line for causing the operation and locking of the set relay, a third relay operated over said line for deactuating the locked set relay, means whereby like directive operation over the line will cause only the second relay or only the third relay of said second and third relays to operate depending upon if the set relay is non-actuated or is locked actuated, respectively, a tone source for each said second and third relays, and means for causing the specific tone source

to be applied audible on the line to indicate which said relay actuated responsive to the directive operation.

40. In a telephone system, a telephone line, two relays for said line, means for directively operating one or the other of said relays over the line responsive to like directive operations therefor, and means for applying a specific signal to the line responsive to the directive operation to indicate which said relay operated responsive to said directive operation.

41. In a telephone system, a telephone line, two relays for said line, means for directively operating one or the other of said relays over the line responsive to like directive operations therefor, means for applying a specific signal to the line responsive to the directive operation to indicate which said relay operated responsive to said directive operation, and means whereby again effecting a like directive operation will cause a different one of said two relays to operate from the one operated last before.

42. In a telephone system, a called line, means for extending connection to said line, a hunting switch, means operated responsive to extending connection to the called line for causing the hunting switch to find the called line, a relay specific to the called line operated responsive to last said operation, a second called line, switch mechanism for extending connection from said called line to said second called line, an impulse sending device, and means for causing the impulse sending device to send a specific train of impulse series to directively operate the switch mechanism to extend the connection from the first said called line to the said second called line responsive to the operation of said relay.

43. In a telephone system, a plurality of called lines, means for extending connection to a random one of said lines, a hunting switch, means operated responsive to extending a connection to said random line for causing the hunting switch to find the latter said line, a relay specific to each said lines operated responsive to last said operation wherein only the relay corresponding to the found line will operate, switch mechanism for extending connections away from first said called line, an impulse sending device, and means for causing the impulse sending device to send impulses to directively operate the switch mechanism to extend the connection from the particular first said called line connected to a specific answering outlet depending upon which one of said first called lines was connected to, under control of the relay operated, and means whereby the impulse sending device can likewise directively operate other switch mechanism responsive to another of first said called lines being connected to wherein the hunting switch will find the last referred to line, while the first said extension is maintained.

44. In a telephone system, a plurality of lines, a first group of finder switches, a second group of finder switches, means operated responsive to initiating a call on a random one of said lines for causing a random one of the finder switches of the first group to hunt for and seize the said random line, means operated responsive to the said seizure for causing a random one of the finder switches of said second group to hunt for and seize the said random finder switch of said first group, a specific wiper on each finder switch of said first group for each finder switch of said second group, a relay individual to each said line also individual to each finder switch of said second group, and means whereby only the sole relay corresponding to the line having the initiated call of the finder switch of said second group that has seized the finder switch of said first group having seized the line having the initiated call will be caused to operate.

45. In a telephone system, a plurality of lines, a first group of finder switches, a second group of finder switches, means operated responsive to initiating a call on a random one of said lines for causing a random one of the finder switches of the first group to hunt for and seize the said random line, means operated responsive to the said seizure for causing a random one of the finder switches of said second group to hunt for and seize the said random finder switch of said first group, a specific wiper on each finder switch of said first group for each finder switch of said second group, a relay individual to each said line also individual to each finder switch of said second group, means whereby only the sole relay corresponding to the line having the initiated call of the finder switch of said second group that has seized the finder switch of said first group having seized the line having the initiated call will be caused to operate, an impulse sending device individual to each finder switch of said second group, and means whereby the impulse sending device concerned will send a specific series of impulses with correspondence to the particular relay operated of the finder switch to which the relay is individual.

46. In a telephone system, a plurality of lines, a group of finder switches, a second finder switch, means operated responsive to initiating a call on a random one of said lines for causing a random one of the finder switches of the group to hunt for and seize the said random line, means operated for causing the second finder switch to hunt for and seize the said random finder switch of said group, a specific wiper on each said finder switch of said group for said second finder switch, a relay individual to each said line also individual to the said second finder switch, and means whereby only the sole relay corresponding to the line having the ini-

tiated call of said second finder switch that has seized the finder switch of said group having seized the line having the initiated call will be caused to operate.

- 5 47. In an automatic telephone system, a group of finder switches, lines commonly accessible from said switches, means whereby only a single said switch can hunt at any time, means whereby said switches will only hunt in predetermined order with respect to 10 any of said switches which may be in seized condition, means whereby initiating a call on a random said line will cause one of said switches to hunt for and seize a calling line, means for applying a signal to any said line initiating a call when all said switches are then in seized condition, and means for applying said signal only to lines upon which a call is then initiated.
- 20 48. In an automatic telephone system, a calling line, a called line, a train of automatic switches directly linked to form a temporary connection from the calling line to the called line, automatic means operated over the calling line for causing the restoration from said train of all of said switches of the connection, automatic means operated over the called line for causing the restoration from said train of all of said switches of the connection, and means whereby said restoration from said train of all of said switches of the connection will be caused by the one said automatic means first operated.

- 35 49. In an automatic telephone system, a calling line, a called line, a train of automatic switches directly linked to form a temporary connection from the calling line to the called line, a release trunk conductor, means depending upon maintaining a predetermined potential of said release trunk for maintaining certain of the said switches which are positioned antecedent of the switch of said train positioned remotest from the calling line in the train, and means controlled 40 over the calling line and also independently over the called line for removing said potential by control over the corresponding said line.

- 50 50. In a telephone system, a line, a switch mechanism for said line, means for extending connection to said line via circuits of said switch mechanism responsive to automatically directing a call extension in accordance with the designation of said line, and means 55 for operating said switch mechanism over said line to cause a call extension thereafter automatically directed in accordance with the designation of said line, to be diverted to another line wherein the talking conductors 60 of the first said line are unconnected with respect to the last said connection.

51. In a telephone system, a line, a switch mechanism for said line, means for extending connection to said line via circuits of said 65 switch mechanism responsive to automatical-

ly directing a call extension in accordance with the designation of said line, means for operating said switch mechanism over said line to cause a call extension thereafter automatically directed in accordance with the 70 designation of said line, to be diverted to another line wherein the talking conductors of the first said line are unconnected with respect to the last said connection and means operated over the first said line for restoring the operated state of the switch mechanism.

52. In an automatic telephone system, a called line outlet, automatic switches for selecting the outlet, means whereby a plurality of said switches may be in simultaneous selective relation to the outlet, and means operated over the said outlet for causing the switches in selective relation to said outlet to at will seize said outlet, but only one at a time, regardless of how many said switches 85 are in selective relation to the outlet.

53. In an automatic telephone system, a called line, a bar terminal of the called line, a calling line, automatic switch mechanism terminating the calling line for seizing the 90 called line and for applying a specific potential to the bar terminal of the called line to prevent subsequent connection to the called line, automatic means in the switch mechanism operated over the called line for removing the said specific potential from the bar terminal of the 95 called line and for applying a specific potential to the bar terminal of the called line, and automatic means in the switch mechanism operated over the called line independent of any operation on the calling line for removing the said specific potential from the bar terminal of the 100 called line.

54. In a telephone system, a relay having a locking electro-magnet and an unlocking electro-magnet, an operating conductor, 105 means whereby applying a predetermined potential to said operating conductor will operatively energize the locking electro-magnet to actuate and lock the relay, and means whereby responsive to removing said predetermined potential from the operating conductor and thereafter applying a predetermined potential to said operating conductor will operatively energize the un-locking 110 electro-magnet to unlock the relay.

55. In a telephone system, a relay having a locking electro-magnet and an unlocking electro-magnet, an operating conductor, means whereby applying a predetermined potential to said operating conductor will operatively energize the locking electro-magnet to actuate and lock the relay, means whereby removing said potential from the operating conductor will not affect the relay, and means whereby responsive to re-applying a predetermined potential to said operating conductor will operatively energize the un-locking electro-magnet to unlock the 125 relay.

56. In a telephone system, a relay, an op- 130

erating conductor, means whereby applying a predetermined potential to said operating conductor will actuate the relay from normal condition and lock the relay in actuated condition, means whereby removing said potential will leave the relay locked in actuated condition, and means whereby thereafter applying a predetermined potential to the operating conductor will cause the relay to 10 thereupon unlock to its normal condition.

In witness whereof, I hereunto subscribe my name this 25th day of February, 1928.

HERBERT M. FRIENDLY.

- erating conductor, means whereby applying a predetermined potential to said operating conductor will actuate the relay from normal condition and lock the relay in actuated condition, and means whereby removing said potential will leave the relay locked in actuated condition, and means whereby thereafter applying a predetermined potential to the operating conductor will cause the relay to thereupon unlock to its normal condition.

10 In witness whereof, I hereunto subscribe my name this 25th day of February, 1928.

HERBERT M. FRIENDLY.

DISCLAIMER

1,806,288.—*Herbert M. Friendly*, Chicago, Ill. AUTOMATIC TELEPHONE SYSTEM. Patent dated May 19, 1931. Disclaimer filed October 9, 1933, by *Milton S. Friendly*, and *Central Republic Trust Company*, as coexecutors of the estate of *Herbert M. Friendly*, deceased.

Hereby enter this disclaimer to the claims in said specification which is in the following words, to wit:

“20. In an automatic telephone system, a called line, a plurality of automatic switches for linking a tandem connection to the terminals of the called line, a back release circuit for applying switch sustaining ground back from the last switch linked into the connection, and means controlled over the called line for removing said ground to thereby cause said plurality of switches to restore from the operated condition in the connection.

“21. In an automatic telephone system, a called line, a plurality of automatic switches for linking a tandem connection to the terminals of the called line, means controlled over the calling line for maintaining ground applied back from the last switch linked into the connection to sustain the connection to the said last switch, and means controlled over the called line for removing said ground applied from the said last switch while the connection to said last switch is sustained for breaking down the connection to said last switch responsive to the removal of said ground.”

“48. In an automatic telephone system, a calling line, a called line, a train of automatic switches directly linked to form a temporary connection from the calling line to the called line, automatic means operated over the calling line for causing the restoration from said train of all of said switches of the connection, automatic means operated over the called line for causing the restoration from said train of all of said switches of the connection, and means whereby said restoration from said train of all of said switches of the connection will be caused by the one said automatic means first operated.

“49. In an automatic telephone system, a calling line, a called line, a train of automatic switches directly linked to form a temporary connection from the calling line to the called line, a release trunk conductor, means depending upon maintaining a predetermined potential of said release trunk for maintaining certain of the said switches which are positioned antecedent of the switch of said train positioned remotest from the calling line in the train, and means controlled over the calling line and also independently over the called line for removing said potential by control over the corresponding said line.”

“53. In an automatic telephone system, a called line, a bar terminal of the called line, a calling line, automatic switch mechanism terminating the calling line for seizing the called line and for applying a specific potential to the bar terminal of the called line to prevent subsequent connection to the called line, automatic means in the switch mechanism operated over the called line for removing the said specific potential from the bar terminal of the called line, and automatic means in the switch mechanism operated over the called line independent of any operation on the calling line for removing the said specific potential from the bar terminal of the called line.”

[Official Gazette November 7, 1933.]

DISCLAIMER

1,806,288.—*Herbert M. Friendly*, Chicago, Ill. AUTOMATIC TELEPHONE SYSTEM. Patent dated May 19, 1931. Disclaimer filed October 9, 1933, by *Milton S. Friendly*, and *Central Republic Trust Company*, as coexecutors of the estate of *Herbert M. Friendly*, deceased.

Hereby enter this disclaimer to the claims in said specification which is in the following words, to wit:

“20. In an automatic telephone system, a called line, a plurality of automatic switches for linking a tandem connection to the terminals of the called line, a back release circuit for applying switch sustaining ground back from the last switch linked into the connection, and means controlled over the called line for removing said ground to thereby cause said plurality of switches to restore from the operated condition in the connection.

“21. In an automatic telephone system, a called line, a plurality of automatic switches for linking a tandem connection to the terminals of the called line, means controlled over the calling line for maintaining ground applied back from the last switch linked into the connection to sustain the connection to the said last switch, and means controlled over the called line for removing said ground applied from the said last switch while the connection to said last switch is sustained for breaking down the connection to said last switch responsive to the removal of said ground.”

“48. In an automatic telephone system, a calling line, a called line, a train of automatic switches directly linked to form a temporary connection from the calling line to the called line, automatic means operated over the calling line for causing the restoration from said train of all of said switches of the connection, automatic means operated over the called line for causing the restoration from said train of all of said switches of the connection, and means whereby said restoration from said train of all of said switches of the connection will be caused by the one said automatic means first operated.

“49. In an automatic telephone system, a calling line, a called line, a train of automatic switches directly linked to form a temporary connection from the calling line to the called line, a release trunk conductor, means depending upon maintaining a predetermined potential of said release trunk for maintaining certain of the said switches which are positioned antecedent of the switch of said train positioned remotest from the calling line in the train, and means controlled over the calling line and also independently over the called line for removing said potential by control over the corresponding said line.”

“53. In an automatic telephone system, a called line, a bar terminal of the called line, a calling line, automatic switch mechanism terminating the calling line for seizing the called line and for applying a specific potential to the bar terminal of the called line to prevent subsequent connection to the called line, automatic means in the switch mechanism operated over the called line for removing the said specific potential from the bar terminal of the called line, and automatic means in the switch mechanism operated over the called line independent of any operation on the calling line for removing the said specific potential from the bar terminal of the called line.”
